UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,403,861.

Specification of Letters Patent. Patented Jan. 17, 1922.

Application filed December 29, 1916. Serial No. 139,511.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to electrical controlling systems, and particularly to electrical controlling systems for automatic or semi-automatic telephone exchanges.

In telephone exchange systems in which an impulse controlling device, such as a sender, controls the operation of selector switches by means of which connections may be established, it has been the practice to provide a plurality of sending units each composed of the sender proper and the means by which the number of effective operations of the sender may be determined. In order to obviate the necessity of providing one sending unit for each trunk leading to a selector, it has been proposed to provide automatically operating switching devices, such as cord finders, sender selectors, etc., by means of which a sending unit may be selectively associated with any one of a plurality of trunks or link circuits leading to selector switches. In such systems a position or station from which the operation of the selector switches is controlled must be equipped with at least one sending unit, which may be associated by manual or automatic means with a trunk leading to the selector switch to be set.

In order to do away with the necessity of providing an impulse controlling device at each operator's position in a semi-automatic telephone exchange, systems were designed to provide one constantly operating impulse controlling device for the whole exchange, and to connect in multiple each operator's keyboard to the common controlling device. The mentioned multiple connection of the keyboards renders this arrangement expensive.

It is the object of the present invention to reduce the cost of electrical controlling systems, applicable particularly to automatic and semi-automatic telephone exchanges by reducing and simplifying the impulse controlling units provided for the control of selector switches.

In its broadest aspect, the present inven-

tion may be defined as relating to an electrical controlling system in which a secondary controlling device such as a sender of the impulse sending or receiving type by which the setting of selectively operable switches may be controlled, is normally not associated with a primary controlling device by means of which its operation may be determined, means being provided for effecting the association between the sender and the controlling device.

According to one feature of the invention, an impulse sending or receiving device having a normal position and a plurality of operating positions for controlling the setting of selector switches, may be variably operated in accordance with the adjustment of a controlling device, such as a keyboard, normally disassociated therefrom.

According to another feature of the invention, any one of a plurality of variably operable impulse sending or receiving devices by which the setting of the selector switches is controlled, may be variably adjusted for operation by any one of a plurality of controlling devices selectively associable therewith. By means of this arrangement, it is possible to provide, for instance, at each semi-automatic operator's position, one controlling device, such as a keyboard, and to provide a plurality of variably adjustable impulse sending or receiving devices less in number than the operators' positions.

A further feature of the present invention contemplates the use of a controlling device at each of a plurality of operators' positions, and impulse sending or receiving devices less in number than said operators' positions and associable with any one of said plurality of positions, each of said impulse sending or receiving devices being composed of a sender proper arranged to send or receive electrical impulses for the purpose of controlling the operation of selector switches, and a registering device associated with said sender and variably operable in accordance with the adjustment of any one of said controlling devices for the purpose of determining the operation of the sender.

A still further feature of this invention contemplates the use of a plurality of variably adjustable controlling devices, any one of which may be associated with any one of a plurality of variably operable impulse sending or receiving devices, a particular

controlling device being associable with an idle one of the sending devices in response to the taking into use of a link or cord circuit.

5 Other features of the invention have to do with the arrangement of the controlling device by which the setting of the sending or receiving device may be determined by variations in the character of current, with the 10 registering device which is responsive to currents of various character, such as low and high potential currents, with the arrangement of the sending or receiving device, the operation of which may be corrected by a so-called translating means, and with various other circuit combinations and arrangements, the character of which will be set forth in the following description of a preferred embodiment of the present invention and the appended claims.

It will be obvious to those skilled in the art that the use of the present invention is not limited to the particular type of switching and controlling devices disclosed, but is 25 equally well applicable to systems in which no registering devices are interposed between the sender and the operator's keyboard and to systems in which the sender is of the directive rather than the revertive- 30 impulse type.

Figs. 1 to 11 of the drawings taken together illustrate diagrammatically a semi-mechanical telephone exchange system embodying the various features of the present 35 invention. The order in which the drawings should be considered is indicated in Fig. 12. Fig. 13 is a schematic showing of the arrangement of the terminals of the selector switches. This figure should be 40 consulted when considering the "translating" system to be hereinafter set forth.

The reference numbers are used in the following manner: 1-99 in Fig. 11; 100-199 in Figs. 1 and 9; 900-999 in Fig. 10; and in 45 the other figures the hundreds digits of the numbers correspond to the number of the figure. For the sake of convenience, the name used in the description for designating certain switching devices is displayed 50 in the drawings adjacent to the showing of such devices. SN and MG designate sensitive and marginal relays, and H and L high and low wound resistances, respectively.

55 Selector switches.

The selector switches used in this system are of the so-called power-driven panel type described in United States Patent No. 60 1,123,696 to E. B. Craft and J. N. Reynolds. For the purpose of distinguishing the various selector switches from each other, they will be hereinafter referred to in the following manner: District selector 65 (Fig. 1), office selector (Fig. 9), incoming

selector (Fig. 10), final selector (Fig. 11), cord finder, (Fig. 5) and sender selector (Fig. 5). Each of these selector switches has a vertically movable brush rod carrying brushes arranged to wipe over a commutator plate, and thus control the operation of the respective selector switches, and wipers arranged to engage contacts of a terminal bank, by means of which connections may be established. With the exception of the sender selector, which carries only one set of wipers, all the selectors referred to carry five sets of wipers, only one set of wipers being shown in the drawings. The terminal banks of the district, office, incoming and final selectors and of the cord finder, comprise 500 rows of terminals divided into five sections, each of the sections comprising one hundred rows of terminals. Each set of wipers is arranged to engage any row of terminals in a certain section, but rests normally below the first row of terminals of its respective section. The wipers of a set are normally held apart by means of a cam, whereby they are out of the path of the terminals. By means of a tripping device associated with each of the selectors, any one of the wiper sets may be tripped to move its wipers into the path of the terminals of its respective section. The tripping device of the district selector and cord finder is of the same type as described in United States Patent No. 1,177,044 to J. L. McQuarrie, and the tripping device shown in association with the office, incoming and final selectors is of the type described in the above mentioned Patent No. 1,123,696. The difference between the two types of tripping device is that whereas, in the former, five magnets are arranged to control 105 the tripping of certain wipers of any one of a plurality of selector switches, in the latter each selector is provided with one tripping magnet arranged to trip any one of its five sets of wipers.

The brush rod of the sender selector carries a single set of wipers which are always in a tripped position and rest normally on the lowermost row of terminals of a terminal bank. The wipers of the other selectors are tripped only when they are moved out of normal, but before they reach the lowermost terminals of their respective terminal sections.

55 Sequence switches.

The sequence switches shown in this system are of the type described in United States Patent No. 1,127,808. Sequence switches 108, 152, 913 and 10 control, by 125 means of their contacts, the circuits of the district, office, incoming and final selectors. All the sequence switch contacts shown in Fig. 1, as also in Figs. 9, 10 and 11, are controlled by the sequence-switch shown in that 130

figure. In Fig. 2, two sequence switches 202 and 210 are indicated. Sequence switch 202 is the listening key sequence switch and controls the contacts shown below the horizontal dotted line in Fig. 2, and sequence switch 210 is the key-control sequence switch controlling the contacts shown above the dotted line in this figure. Sequence switch 516 (Fig. 5) controls the circuits of the 5 horizontal dotted line in Fig. 2, and sequence switch 210 is the key-control sequence switch controlling the contacts shown above the dotted line in this figure. Sequence switch 516 (Fig. 5) controls the circuits of the 10 cord finder and the sender selector. All the sequence switch contacts shown in this figure, with the exception of those within the dotted rectangle, are controlled by this sequence switch. The latter mentioned contacts are controlled by an allotter 583 of the 15 sequence switch type. Sequence switches 613 and 600 (Fig. 6) control, by means of their contacts shown to the left and right of the vertical dotted line of this figure, the 20 circuits of a sender, and the circuits of a plurality of registers, respectively. The sequence switch contacts shown in Fig. 7 are controlled by sequence switch 706. This 25 sequence switch will be referred to as a class register controller.

Keyboard.

The operator's keyboard is shown in Figs. 3 and 4. When, in any of the rows, a key is 30 depressed, it is locked by mechanical means, which may be released in response to the energization of a magnet 342, one being provided for each row of keys. There are nine 35 rows of keys referred to as the office, tandem hundreds, tandem tens, tandem units, thousands, hundreds, tens, units and stations keys. Each row, with the exception of the office 40 and stations keys, comprises keys numbered 0 to 9, each key controlling as many contacts 45 as is necessary for controlling the selectors and registers. The number of office keys depends on the traffic requirements. The office keys are the equivalents of the tandem hundreds, tandem tens and tandem units 50 keys; that is to say, the depression of one office key results in the same combination of impulses as the depression of a certain combination of tandem hundreds, tens and units keys. One office key is provided for controlling the seizure of a trunk leading to an important office, whereas other offices may be reached by depressing a prescribed combination of tandem keys.

Registers.

Figs. 7 and 8 represent ten registers. 55 These registers will be referred to as: 1, district group or tandem tens; 2, office brush; 3, office group or tandem units; 4, class; 5, 60 incoming brush; 6, incoming group; 7, final brush; 8, final tens; 9, final units; and 10, stations registers. With the exception of the class and incoming group registers, each register comprises three relays, two of the 65 relays being of a marginal character and one

of the relays sensitive. The incoming group register comprises one sensitive and one marginal relay, and the class register, two sensitive and three marginal relays. Each of the register relays is provided with a 70 locking winding, and depending on the combination in which the relays of a certain register are actuated, the operation of the sender is determined.

Sender.

75

The sender (Fig. 6) comprises a pair of wipers 635 and 636 arranged to be moved step-by-step over a circle of terminals in the direction indicated by the arrow, in response to each complete operation (energization and deenergization) of a magnet 634. The terminals are divided into four sections A, B, C and D. The terminals of sections A and B are connected to conductors 657 and 642, respectively. The five terminals of sections C and D are numbered 0 to 4, and the terminals of these two sections designated by the same numerals are connected in multiple. The two terminals numbered 0 are interconnected by means of sequence switch springs 664 and 665 in certain positions of sequence switches 600 and 613. Magnet 634 may be energized and deenergized under the control of a stepping relay 632. A relay 633 controls the stopping of the sender wipers in a certain position determined by the setting of the various registers. The numerals appearing in the circles at the contacts of the various register relays indicate the terminal of the sender to which those contacts are connected.

Translation.

80

In the system disclosed, by means of the district and office selectors, a ten-thousand 105 line exchange may be selected. The called line terminating in this exchange is reached by the incoming and final selectors. Each of the five sections of terminals in the terminal banks (Fig. 13) of the district and office 110 selectors is divided into ten groups containing the terminals of trunks leading to various office and incoming selectors, respectively. One group contains ten sets of terminals. Each section of the incoming selector is divided into four groups of terminals, each group containing twenty-five sets of terminals. Each section of the terminal bank of a final selector is divided into ten 115 groups, each containing ten sets of terminals. For the purpose of providing means for controlling the release of the district, office and incoming selectors, if all the trunks of a group are busy, an overflow contact must be provided for each group of trunks. 120

Each set or row of terminals in the terminal bank of the final selector serves as a calling terminal for a subscriber's line. In the present case, it will be assumed that the final selector, shown in Fig. 10, is one of a plu- 125 130

rality of selectors that serves for seizing one of the lines numbered 9500 to 9999 (see also Fig. 13). The first section contains the terminals of lines 9500 to 9599, the second section 9600 to 9699, the third section, 9700 to 9799, the fourth section, 9800 to 9899, and the fifth section, 9900 to 9999.

Any one of the final selectors serving these five hundred lines may be reached by means 10 of any one of a plurality of incoming selectors. The trunks terminating in the various sections of the terminal bank of an incoming selector are numbered as follows: section No. 1, 0 to 1999; section No. 2, 2000 to 3999; section No. 3, 4000 to 5999; section No. 4, 6000 to 7999; and section No. 5, 8000, 9999. If the number of the desired line is 9876, then it is necessary to trip the fifth set of brushes of the incoming selector, because this set of 20 brushes serves the trunks terminating in the fifth section (8000 to 9999). The first group of trunks in this section leads to final selectors through which access may be had to subscribers' lines numbered 8000 to 8499, the second group of trunks leading to final selectors containing terminals numbered 8500 to 8999, the third group to final selectors through which access may be had to 9000 to 9499, and the fourth group contains trunks 30 leading to final selectors through which access may be had to subscribers' lines 9500 to 9999. In the present case, it will be necessary to step the wipers of the incoming selector by four steps, and then operate it to select and seize an idle one of the trunks leading to the final selector. All but the fifth set of wipers of the incoming selector are held out of the path of the terminals of their respective sections. In the final selector, it 40 will be necessary to trip the fourth set of wipers arranged to engage the terminals of the section 9800 to 9899, and the final wipers must then be stepped by eight steps, whereby the fourth set of wipers is positioned below the terminal No. 9870. By causing the final wipers to move seven steps the terminal No. 9876 will be seized by the fourth set of wipers.

The arrangement of the trunk terminals 50 in the various sections of the terminal banks of the district and office selectors depends on traffic conditions, and in the present case, it will be assumed that the incoming selector shown in Fig. 10 is accessible in response to the depression of the B office key controlling the tripping of the second set of wipers of the district selector, the stepping of these wipers onto the ninth group of terminals in the second section of the terminal bank and 60 then the tripping of the fourth set of wipers of the office selector, and the setting of these wipers onto the second group of terminals in the fourth section of the terminal bank of the office selector.

65 In view of the fact that the numerical

designations of the terminals of sections C and D of the sender are identical, and that the various registers may control the sender to stop in one out of five positions, means must be provided for causing the sending of 70 additional impulses if the selector must be stepped by nine steps, as in the case of the district selector, or generally if it is desired to send more than five selective impulses. This is done by providing translating relays, such as 742 and 721 (Fig. 7), and 832 and 821 (Fig. 8). Depending on the numerical designation of the key actuated, these translating relays are operated to determine on which of the two terminals (1-1, 75 2-2, etc.) the sender wiper 635 should stop; that is to say, if it is desired to step the wipers of the district selector by nine steps, then the district group register relays are set so as to close a circuit for relay 633 when the sender wiper 635 has been moved by four steps, and reaches terminal No. 3 in section C. In order to cause this wiper 635 to step onto terminal No. 3 in section D of the terminal bank of the sender 80 and thus take nine steps from its normal position, relay 721 is energized so as to insure the taking of five additional steps by the sender wipers. If relay 742 is energized, then the sender takes five additional steps 85 when the office group impulses are sent. If relay 832 is energized, the sender takes five additional steps when the final tens impulses are sent, and in response to the energization of relay 821, the sender is caused to take five 90 additional steps when the final units impulses are sent. In view of the fact that a section of the terminal bank of the incoming selector is divided into four groups, it is not necessary to provide translating means for 95 controlling the sending of incoming group impulses.

Brief outline of operation.

A subscriber at station 100 (Fig. 1), desiring to obtain a connection with a subscriber at station 33 (Fig. 11) located in a distant semi-mechanical exchange causes the actuation of a signal CL at an operator's position. The operator extends the calling line by an 110 idle one of a plurality of cord or trunk circuits such as 105, provided at her position, one end of this cord terminating in an answering plug 101, and the other in the wipers of the district selector.

In response to the extension of the calling line, the listening key sequence switch 202 individual to the cord 105 taken into use, associates the operator's telephone set 200, common to a plurality of cords, with the 115 cord 105. There are a plurality of cord finders and sender selectors similar to those shown in Fig. 5. Under the control of allotter 583, one cord finder and its associated sender selector, are held in readiness 120 125 130

for service. As soon as the sequence switch 108 moves into position 2, the preselected cord finder and the associated sender selector, the sequence switch 516 of which is in position 1, are started. The cord finder hunts for terminals representing the cord 105, and when these are reached, the cord finder is stopped. The sender selector hunts for an idle one of a plurality of senders. The relay arrangement shown within the dotted rectangle in the lower right-hand portion of Fig. 5, is provided in common for a plurality of cord finders and operates to prevent the tripping of a plurality of brushes on a cord finder if a plurality of sequence switches like 108 are moved simultaneously into position 2. The arrangement shown within the dotted rectangle in the lower left-hand portion of Fig. 5, is individual to a group of cord circuits 105 and controls the operation of the arrangement in the lower right-hand portion of Fig. 5, and may prevent the operation thereof if only one call is coming in at a time, and thus there is no danger of two sets of cord finder wipers being tripped.

At each operator's position there is provided one keyboard with its associated controlling apparatus, shown in the upper portion of Fig. 2 and in Figs. 3 and 4. In response to the movement of any one of the listening key sequence switches provided at an operator's position into the listening-in position (7) and the movement of the sequence switch 108 into position 2, the operator's keyboard is seized for use; that is to say, operatively associated with the sending and registering arrangement shown in Figs. 7, 6 and 8 through the cord finder and sender selector.

The operator then depresses the keys designating the number of the called line. If the called subscriber is located in a semi-mechanical exchange that may be reached in response to the depression of the office key B, the operator does not depress any of the tandem keys, neither does she depress a stations key. Assuming that the called subscriber's number is B-9876, the operator depresses the No. B office, No. 9 thousands, the No. 8 hundreds, No. 7 tens, No. 6 units, and the start key 414. The depression of the office key results in the energization of certain of the relays shown in Fig. 3. These relays may also be controlled to operate in a certain combination in response to the depression of the tandem keys. As a result of the actuation of a certain combination of the mentioned relays and due to the particular wiring of the thousands, hundreds, tens and units keys, the operations of the marginal relays of the registers and that of the translating relays are determined. Certain of the marginal register relays may be prevented or permitted to operate by connecting the low resistances 319 or 339 or the

high resistances 363 or 327, in series with such relays, or by completing or not completing the circuit of these relays through certain key contacts during the setting of the registers. The other marginal register 70 relays are energized or left deenergized depending on the insertion of both windings of relays 220 and 233, or only the low resistance left-hand windings of these relays in series with such relays.

The depression of the office key B causes the tripping of the second set of wipers of the district selector, the setting of the class and district group registers, the energization of relay 721, and the setting of the 80 office brush and office group registers. The shifting of the control of the office key B from one register to the other is accomplished by the key control sequence switch 210 and the register control sequence switch 85 600. In position 2 of these sequence switches, the class register is set; in position 3, the district group register; in position 4, the office translation is controlled; in position 5, the office brush register is set; 90 and in position 6, the office group register is set.

The setting of the class register depends on the character of the connection desired. In the present case, when a semi-mechanical connection is desired, the class register is left in position 1 and exercises a certain control on the operation of the system to be set forth during the detailed description of the operation of the system.

After the setting of the office group register, the sequence switches 210 and 600 remain in position 7 until moved into position 8, the former in response to the depression of the start key, and the latter under the control of class register sequence switch 706. If the class register sequence switch 706 is left in position 1, the sequence switch 600 is moved into position 8 for permitting the setting of the incoming brush register under the control of the depressed thousands key. If another type of connection is desired, then the class register is moved out of its normal position and moved into another position than 8.

The depressed thousands key causes also the setting of the incoming group register in position 9 of sequence switches 210 and 600, in cooperation with the depressed hundreds keys. The actuated hundreds key 110 controls in position 10 of sequence switches 210 and 600, the setting of the final brush register.

The operated tens key causes in position 11 of sequence switches 210 and 600 the setting of the tens register, and in position 12 of these sequence switches, under the control of the depressed tens and units keys, the relays 832 and 821 are energized if translation is desired.

The units key controls the setting of the units register in position 13 of sequence switches 210 and 600.

In position 14 of the sequence switches 5 210 and 600, the stations register is set under the control of a start key 416, but in view of the fact that in a semi-mechanical call the sending out of stations impulses is not necessary, the class register controller 10 will prevent the sending of these stations impulses.

The circuits of the register relays are so arranged that, for instance, the final brush register relays close a circuit for relay 633, 15 when the sender reaches terminal No. 0, if the relays 812 and 811 are energized and the relay 814 deenergized. The relay 633 may become energized when sender wiper 635 engages terminal No. 1, if all three relays 20 811, 812 and 814 are energized; when sender wiper 635 engages terminal No. 2, if all the three register relays are deenergized; when wiper 635 engages terminal No. 3, if relays 812 and 811 are deenergized and relay 25 814 is energized; and when the sender wiper engages terminal No. 4, if relay 812 is energized and relays 811 and 814 are deenergized. The relays of the other registers control the stopping of the sender in a similar manner. The incoming group register, 30 however, controls the stopping of the sender with wiper 635 on terminal No. 3 when the sensitive and marginal relays are deenergized; on terminal No. 2, when the sensitive relay is deenergized and the marginal relay energized; on terminal No. 1, when the sensitive relay is energized and the marginal relay deenergized; and on terminal No. 0 when both relays are energized.

40 After the setting of the class, district group, office brush and office group registers and in position 2 of sequence switch 613, the district selector is operated and sends impulses over a fundamental circuit to operate the magnet 634 through the agency of a stepping relay 632. After the sender wipers have been stepped by nine steps, the relay 633 becomes energized, opens the fundamental circuit, causes the restoration of 45 the sender and the advance of sequence switch 613. During the restoration of the sender the district selector automatically selects an idle trunk leading to the office selector. In position 4 of the sequence switch 50 613, four impulses are received by the sender under the control of the office selector, and in accordance with the setting of the office brush register. After the receipt of the four impulses the relay 633 operates in 55 the above described manner and advances the sequence switch 613 into position 6. Two office group impulses are received from the office selector in accordance with the setting of the office group register and the relay 633 operates to advance the sequence 60 65

switch 613 into position 8. In positions 8, 10 and 12 of the sequence switch 613, the tandem hundreds, tandem tens, and tandem units impulses may be sent out. In view of the fact that, in the present case, the 70 sending of such impulses is not desired, due to the setting of class register sequence switch 706, the sequence switch 613 is advanced from position 7 into position 14. In the meantime, the office selector selected an 75 idle trunk leading to the incoming selector. After the registers shown in Fig. 8 have been set, the incoming selector sends five impulses into the sender in accordance with the setting of the incoming brush register, 80 whereupon the sequence switch 613 is advanced to position 16 in the above described manner, for receiving the group impulses in accordance with the setting of the group register under the control of the incoming 85 selector, whereupon sequence switch 613 is moved into position 18. The incoming selector hunts for an idle trunk in the selected group. Then the sender receives four impulses from the final selector in accordance 90 with the setting of a final brush register, whereupon the sequence switch 613 is moved again into position 2, but, due to the fact that the sequence switch 600 was moved in the meantime into position 16, the sender receives now the final tens impulses instead of the district group impulses. After the receipt of eight impulses under the control of the final selector, the sequence switch 613 is moved into position 4 and receives now, instead of the office brush impulses, the final units impulses under the control of the final selector. The sender sequence switch 613 is moved then into position 6, but, under the control of class register sequence switch 706, 105 the sending of stations impulses is prevented. The sender, the registers, the sender selector, the cord finder, and the keyboard are then released to normal and ready for controlling the setting up of another connection. 110

Detailed description.

A subscriber at substation 100 (Fig. 1), desiring to obtain a connection with a subscriber at station 33 (Fig. 10) removes his receiver from the switchhook, whereupon a line relay LR becomes energized and causes the lighting of a calling lamp CL. An operator, whose head set is indicated at 200, 115 inserts thereupon a plug 101 into an answering jack 102 in which the calling subscriber's line terminates. A circuit is closed thereupon from grounded battery, through the winding of a cut-off relay CO, the sleeve 120 contacts of jack 102 and plug 101 and the winding of relay 103 to ground, and another circuit from the plus pole of battery, through the primary winding of a repeating coil 104, the winding of an answering super- 125 130

visory relay SR, the lower limb of cord circuit 105, the ring contacts of plug 101 and jack 102, the calling substation 100, the tip contacts of jack 102 and plug 101, the upper limb of cord circuit 105 and the primary winding of repeating coil 104 to the minus pole of battery. Relays CO, 103 and SR become energized. The relay CO disconnects relay LR, whereupon lamp CL becomes extinguished.

Relay 103 closes a circuit from ground, through its armature and front contact, conductor 106, the lower right-hand contact of sequence switch spring 201 and the power magnet of sequence switch 202 to grounded battery. Under the control of its normal contact 203, the sequence switch 202 is moved out of position 1 and into position 7. In position 7 of the sequence switch 202, the operator's telephone set 200 is connected by means of sequence switch contacts 204 and 205 to the cord circuit 105, and thus the operator is enabled to converse with the calling subscriber. When the sequence switch 202 reaches position 7, a circuit is closed from ground, through sequence switch contact 206, a conductor 207, the upper right-hand contact of sequence switch spring 107, and the power magnet of sequence switch 108 to grounded battery. Sequence switch 108 is moved out of position 1, and under the control of its normal contact 109, into position 2. Another circuit is closed from ground, through sequence switch contact 208, contact 209 of sequence switch 210 and the winding of a relay 211, to grounded battery. Relay 211 becomes energized and closes a locking circuit for itself through its right-hand front contact and armature and sequence switch contact 208.

As indicated in Fig. 2 of the drawings, the relay 211 is common to a plurality of listening-key sequence switches and thus it may be energized also in response to the closure of a sequence switch contact 208 controlled by another listening-key sequence switch of the operator.

Setting of the cord finder and the sender selector.

Assuming that several cord circuits are simultaneously taken into use by various operators, and thus several sequence switches like 108 are in position 2, a circuit is closed from ground, through the lower right-hand contact of sequence switch spring 112, conductor 111 (Figs. 1, 2 and 5), the lower armature and back contact of a relay 500, the lower armature and back contact of a relay 501, a resistance 502 and the winding of a marginal relay 503 to grounded battery. A similar circuit is closed for the relay 503 by each of the sequence switches corresponding to 108. Each of these circuits includes a resistance like 502 and, for this reason, the

relay 503, which is marginal in operation, is operated. Relays 500 and 501, resistance 502 and the conductors shown in the lower left-hand corner of Fig. 5, are individual to the link circuits 105 of the operator's position. Similar apparatus are individual to each of the other positions. Relay 503 closes a circuit from ground, through its armature and front contact, the armature and back contact of a relay 504, and the back contact and armature of a magnet 505 to grounded battery. Magnet 505 interrupts its own circuit and thus causes, by means of a pawl 506 fixed to its armature, the stepping of wipers 507 and 508 mounted on a ratchet wheel 509. The wipers 507 and 508 are arranged to traverse terminals representing groups of link circuits. As soon as the wiper 508 engages terminal 510 individual to the group in which the link circuit 105 belongs, a circuit is closed from grounded battery, through the winding of relay 504, wiper 508, terminal 510, the lower back contact and armature of relay 501, the lower back contact and armature of relay 500, conductor 111 and sequence switch contact 112 to ground. Relay 504 becomes energized and opens in its back contact the operating circuit of magnet 505, whereupon the wipers are arrested. Relay 504 closes also a circuit from ground, through the armature and front contact of relay 503, its armature and front contact, the armature and back contact of a relay 511, and the left-hand winding of a relay 512 to grounded battery. Relay 512 closes a locking circuit for itself from ground, through its armature, front contact and right-hand winding, wiper 507, a terminal 513 individual to the group of cords 105, the lower winding of relay 501, and the windings of relays 511 and 514 to grounded battery. Relays 511, 514 and 501 become energized. When relay 501 opens in its lower back contact the energizing circuit of relay 503, this relay is maintained energized by a circuit closed through the lower back contact of another relay 501 individual to another group of calling link circuits. Relay 504 becomes deenergized. Relay 514 closes a circuit from ground through its armature and front contact, the upper left-hand contact of sequence switch spring 515, and the left-hand winding of a relay 517 to grounded battery. As will be hereinafter set forth, only one sequence switch like 516 is in position 1 at a time, and for this reason the energization of relay 514 results in the energization of only one relay like 517. Upon the energization of relay 501 a circuit is closed from ground, through the lower right-hand contact of sequence switch spring 112, conductor 111, the lower armature and back contact and the lower armature and front contact of relays 500 and 501 to ground.

respectively, and the winding of a trip magnet 541 to grounded battery. The trip magnet 541, by attracting its armature, moves a trip finger 542 into the path of a catch 543 carried by cam 535. The connection of ground to the lower front contact of relay 501 results also in the shunting out of relay 512, which thereupon becomes deenergized. Before the wipers of set 533 engage the lowest terminals of bank 534 as will be hereinafter set forth, the trip finger actuates catch 543, causing thus cam 535 to be removed from between the wipers; whereupon these wipers are permitted to move in alignment with the terminals of the bank.

Upon the deenergization of relay 504, relay 503 causes magnet 505 to move the wipers 507 and 508 away from terminals 513 and 510. Relay 504 breaks the circuit of magnet 505 in the same manner as above described when wiper 508 finds the terminal individual to the group containing the next calling link circuit.

The wipers of the sender selector 518 are normally resting on a set of contacts in which conductors leading to a sender terminate. Supposing that this sender is busy, as will be hereinafter set forth, ground is connected to terminal 519. For this reason a locking circuit is closed for relay 517, through wiper 520 of the sender selector 518, and the right-hand armature, front contact and winding of the relay 517. Upon the energization of relay 517, a circuit is closed from ground, through the left-hand armature and front contact of this relay, the upper right-hand contact of sequence switch spring 521 and the winding of a relay 522 to grounded battery. Relay 522 closes a circuit from ground, through its right-hand armature and front contact, the lower left-hand contact of sequence switch spring 523 and the power magnet of sequence switch 516 to grounded battery. The sequence switch 516 is thereupon moved out of position 1, and under the control of its normal spring 524, into position 2. A circuit is now closed from grounded battery, through the winding of a magnet 525, the upper contacts of sequence switch spring 526 and the right-hand front contact and armature of relay 522 to ground, and another circuit from ground, through the left-hand armature and front contact of relay 517, the upper left-hand and lower right-hand contacts of sequence switch spring 527, and the winding of a magnet 529 to grounded battery. Magnets 525 and 529 become energized. By attracting its armature magnet 525 presses brush rod 530 of cord finder 531 against a roller 532 constantly rotating in the direction indicated by the arrow. The brush rod 530 carries a plurality of sets of wipers similar to 533. These wipers are arranged to engage the sections of the ter-

minal bank 534 comprising sets of terminals representing cord circuits such as 105, but the wipers of each set are normally held apart by means of a cam like 535. A brush 536, arranged to engage various segments 70 of a commutator plate is also carried by brush rod 530. As soon as the brush rod has been moved in an upward direction far enough to permit brush 536 to engage conducting segment 537, which happens prior 75 to the engagement by the wipers 533 of the lowest row of terminals of the respective bank section, a circuit is closed from ground, through brush 536, conducting plate 537, the right-hand contacts of sequence switch spring 560, the upper front contact and armature of relay 501, and the winding of relay 500 to grounded battery. The relay 500 becomes energized and closes a locking circuit for itself through conductor 111 and sequence switch spring 112, to ground, whereupon relays 501, 511 and 514 become deenergized. Relay 514 closes a circuit from ground, through its armature and back contact, the upper right-hand contact of sequence switch spring 523, and the power magnet of sequence switch 516, to grounded battery, whereupon the sequence switch is moved out of position 2 and into position 3. Relay 511 being deenergized, 85 the relay 512 is permitted to operate under the control of the next calling cord circuit.

When the sequence switch 516 moved out of position 2, relay 522 was maintained energized by a circuit extending from ground, 100 through its winding, the upper left-hand contact of sequence switch spring 521, and the right-hand back contact and armature of a test relay 545 to ground. As soon as the wipers 533 engage the set of terminals 105 representing cord 105, a circuit is closed from ground, through the upper right-hand contact of sequence switch spring 112, a conductor 186, a resistance 212, conductor 213, terminal 546, wiper 574, the lower 110 right-hand contact of sequence switch spring 547, and the windings of relay 545 to grounded battery. If full battery potential exists on terminal 546; that is to say, if no other cord finder engages with its test 115 wiper this terminal, then relay 545, which is marginal in operation, becomes energized and closes a locking circuit for itself through its left-hand armature and front contact, and conductor 213. By short-circuiting its high resistance left-hand winding, this relay decreases the potential on terminal 546, so as to prevent the energization of a test relay associated with another cord finder, when such cord finder tests the 120 terminals representing cord 105. As a precautionary measure, other means are provided in the right-hand armature and front contact of relay 545, and a resistance 548, for decreasing the potential on test termi- 130

nal 546 in position 2 to 2½ of sequence switch 516.

By opening its right-hand back contact, relay 545 opens the circuit of relay 522. 5 This relay, however, remains energized, ground being connected to its winding through brush 536 as long as this brush rests on a conducting plate 549. As soon, however, as the brush 536 engages one of the 10 insulated segments 550, which indicates that the wipers 533 are centered on the selected set of terminals, the relay 522 becomes de-energized and closes a circuit from ground, through its right-hand armature and back 15 contact, the upper left-hand contact of sequence switch spring 523, and the power magnet of sequence switch 516 to grounded battery, for driving this sequence switch out of position 3 into position 4. As soon as 20 relay 522 becomes deenergized, the circuit of magnet 525 is opened, and thus the brush rod 530 is arrested with the wipers 533 in engagement with the selected set of terminals.

25 In position 4 of sequence switch 516, a circuit is closed from ground, through the contact of sequence switch spring 580, the upper left-hand contact of spring 581 and the power magnet of allotter 583, to ground- 30 ed battery. The allotter is moved out of position 1 and under the control of its normal contact 584 into position 2. The allotter closes now the contact of its spring 582 and causes the preselection of a cord finder and 35 a sender selector switch by moving their associated sequence switch out of position 18 into position 1, as will be hereinafter set forth in connection with sequence switch 516.

40 The magnet 529, by attracting its armature, presses brush rod 552 against a roller 553, constantly rotating in the direction indicated by the arrow. The brush rod 552 of sender selector 518 carries a set of wipers 45 554 and a brush 555. The energizing circuit of magnet 529 will be maintained closed while relay 517 is energized, and the upper left-hand and lower right-hand contacts of sequence switch spring 527 are closed. For 50 this reason the wipers 554 continue to move in an upward direction until wiper 520 engages a terminal 551 individual to a sender, the sequence switch 600 of which is in position 1, and maintains the upper contacts of 55 its spring 601 open, and which sender is not occupied by another sender selector. In the latter case, the relay 517, although its above traced locking circuit is open, is then maintained energized by a circuit extending from 60 ground, through its left-hand armature and front contact, the upper left-hand contact of sequence switch spring 527, brush 555, conducting plate 556, the upper right-hand contact of sequence switch spring 515, and the 65 left-hand winding of relay 517 to grounded

battery, as long as brush 555 engages the conducting segment 556. When, however, the brush 555 engages an insulated segment 558, indicating thus that the wipers 554 are centered on the selected set of terminals, relay 517 becomes deenergized, opens the circuit of magnet 529 and closes a circuit from ground, through its left-hand armature and back contact, the lower right-hand contact of sequence switch spring 523, and the power 70 magnet of sequence switch 516 to grounded battery, for moving this sequence switch out of position 4 and into position 15.

75 It may be seen from the above that if a plurality of sequence switches like 108 are moved into position 2 at the same time, then, under the control of the devices and circuits represented in the lower part of Fig. 5, one call is taken care of and the setting of another pair of cord finder and sender selector switches is delayed until the wipers 533 of cord finder 531 are tripped, i. e., until the five sets of wipers carried by brush rod 530, have been moved a sufficient distance so as to prevent the tripping of another set of 90 brushes of this cord finder in response to the energization of another trip magnet, such as 541.

95 If only a single sequence switch like 108 is moved into position 2, it is not necessary to operate the above described barring means. Due to the marginal character of relay 503, it will not operate in response to current flowing through a circuit which contains only one resistance like 502. A circuit will 100 therefore be closed from ground, through the back contact of relay 503, the left-hand armature and back contact of relay 511, the upper winding of the relay 501 individual to a group of cord circuits 105, the upper back contact and armature of relay 500, conductor 585, and the contact of sequence switch spring 110 to grounded battery. Relay 501 becomes energized and closes a circuit from grounded battery, through the 110 windings of relays 514 and 511, the lower winding, front contact and armature of relay 501, the lower back contact and armature of relay 500, conductor 111, and the lower right-hand contact of sequence switch spring 112, to ground. A branch of this circuit extends from grounded battery, through the winding of trip magnet 541 to the lower front contact and armature of relay 501. The relays 514 and 511 and the magnet 541 115 become energized and the switches 518 and 531 are operated in the same manner as above described.

120 Upon the setting of cord finder 531 and sender selector 518, the sequence switches are 125 in the following positions: sequence switch 108 in position 2, sequence switch 202 in position 7, sequence switch 516 in position 15, and all the other sequence switches in position 1.

Adjustment of the keyboard.

Supposing that the called subscriber's number is B-9876, the operator depresses the B office key, the number 9, 8, 7, 6 thousands, hundreds, tens and units keys and a start key 404, respectively, whereupon the keys remain locked in their depressed position.

In response to the depression of office key B, contacts 353, 354, 355 and 356 of this key are closed. The closure of these contacts results in the establishment of the following circuits:

1. From grounded battery, through the winding of a relay 349, contact 353, conductor 357 (Figs. 3, 2 and 1), the winding of a relay 113_a to ground. Relays 113_a and 349 become energized.

2. From ground, through the winding of a relay 214, a conductor 215, the winding of relay 303, contact 354, and the winding of a relay 305, to grounded battery. Relays 214, 303 and 305 become energized.

3. From grounded battery, through a resistance 358, conductor 359, key contact 355, conductor 360, the winding of a relay 311, conductor 312, conductor 215, and the winding of relay 214 to ground. Relay 311 becomes energized.

4. From grounded battery, through the winding of a relay 344, conductor 361, key contact 356, conductor 346, the right-hand winding of a relay 329, the winding of a relay 313, conductors 312 and 215, and the winding of relay 214 to ground. Relays 344, 329 and 313 become energized.

In response to the energization of relay 344, a circuit is closed from grounded battery through the power magnet of sequence switch 210, the upper right-hand contact of sequence switch spring 237, a conductor 264, the left-hand front contact and armature of relay 344, a conductor 263, the left-hand inner front contact and armature of relay 211, a sequence switch contact 262, a conductor 132, and the upper left-hand contact of sequence switch spring 112 to ground. The sequence switch 210 is moved out of position 1, and under the control of its normal contact 265 into position 2.

Setting of the class register.

As soon as sequence switch 210 reaches position 1₂, a circuit is closed from grounded battery, through the relatively low resistance 319, the front contact and armature of relay 303, conductor 231, the lower right-hand contacts of sequence switch springs 230 and 229, the upper contact of sequence switch spring 228, conductor 566, terminal 579, wiper 528, sequence switch contact 565, wiper 540, terminal 539, conductor 620, the upper right-hand contact of sequence switch spring 619, conductor 710, and the left-hand windings of a marginal relay 704 and a sensitive relay 709, to ground. Due to the relatively

low resistance of the circuit, both relays become energized.

In position 1₂ of sequence switch 210, another circuit is closed from grounded battery, through the relatively low resistance 339, the front contact and armature of relay 349, a conductor 362, the upper contacts of sequence switch springs 266 and 226, conductor 227, terminal 578, wiper 576, sequence switch contact 563, wiper 538, terminal 557, conductor 564, the right-hand contact of sequence switch spring 615, a conductor 616, and the left-hand windings of a marginal relay 702 and a sensitive relay 703 to ground. Due to the relatively low resistance of the circuit both relays 702 and 703 become energized.

When the sequence switch 210 reaches position 2, a circuit is closed from ground, through the upper armature and back contact of a relay 219, the low resistance left-hand winding of a relay 220, a conductor 221, the front contact and armature of relay 305, conductor 318, the lower right-hand contacts of sequence switch springs 222 and 223, the upper left-hand contact of sequence switch spring 224, conductor 225, terminal 577, wiper 575, the left-hand contacts of sequence switch spring 560, wiper 544, terminal 559, conductor 561, the upper contact of sequence spring 603, conductor 604, the left-hand winding of a marginal relay 700, conductor 701, the upper right-hand contact of sequence switch spring 605, and the winding of a relay 606, to grounded battery. Relays 220, 606, and, due to the relatively low resistance of the left-hand winding of relay 220, the marginal relay 700, become energized.

Relay 606 closes a circuit from ground, through its armature and front contact, the lower contacts of sequence switch spring 601, and the winding of a relay 608 to grounded battery. Relay 608 closes a circuit from ground, through its lower armature and front contact, the upper left-hand contact of sequence switch spring 609 and the power magnet of sequence switch 600 to grounded battery, for moving this sequence switch out of position 1; under the control of its master contact 668, the sequence switch 600 is moved into position 2. The relay 608 does not become deenergized upon the opening of the lower contacts of sequence switch spring 601, a locking circuit being closed from grounded battery, through the winding, and upper front contact and armature of this relay, conductor 610, terminal 551, wiper 520, the right-hand armature and back contact of test relay 517, and the left-hand contact of sequence switch spring 562, to ground. A circuit is now closed from ground, through sequence switch contact 611, the left-hand contact of sequence switch spring 612 and the power magnet of se- 130

quence switch 613 to grounded battery. Sequence switch 613 is moved out of position 1 and under the control of its normal contact 614 into position 2.

- 5 As soon as sequence switch 600 reaches position 2, a circuit is closed from grounded battery, through the upper contact of sequence switch spring 621, conductor 712, and then through the right-hand windings, 10 armatures and front contacts of relays 700, 704, 709, 702 and 703 in multiple, to ground. These relays remain thus locked up. Due to the fact that all the class-register relays are energized, the circuit which was prepared 15 from ground through sequence switch contact 617, conductor 618 and any one of the sequence switch springs 739, 711, 708 and 740 for the class-register sequence switch 706 and relay 705, will be maintained open 20 in the outer back contacts of the class register relays. The sequence switch 706 remains thus in position 1 and the relay 705 does not become energized.

Normally a shunt is placed around the 25 winding of relay 219, through the lower armature and back contact of this relay and the left-hand back contact of relay 220. As soon as relay 220 becomes energized and opens its left-hand back contact the relay 30 219 is permitted to become energized by current flowing from ground, through its winding, the left-hand contact of a sequence switch spring 218, and a resistance 217 to grounded battery. The ground that was 35 supplied through the upper back contact of relay 219 is now supplied through the left-hand front contact of relay 220 for maintaining the latter energized.

As soon as sequence switch 600 reaches 40 position 2, a circuit is closed from grounded battery, through the power magnet of sequence switch 600, the armature and back contact of a relay 623, the left-hand contact of sequence switch spring 622, and the front contact and armature of relay 606 to ground. The sequence switch 600 moves out of position 45 2 into position 3. Due to the opening of the upper right-hand contact of sequence switch spring 605, relays 606 and 220 become deenergized and the latter closes a 50 circuit from ground through its left-hand armature and back contact, the lower armature and front contact of relay 219, the sequence switch spring 232, the left-hand back 55 contact and armature of relay 233, and the power magnet of sequence switch 210 to grounded battery. The sequence switch moves out of position 2 into position 3, whereby relay 219 becomes deenergized.

60 *Setting of the district group register.*

When the sequence switches 210 and 600 reach position 2 $\frac{1}{2}$, a circuit is prepared from ground through the left-hand windings of 65 a marginal relay 718, and a sensitive relay

717, conductor 625, the upper left-hand contact of sequence switch spring 624, conductor 561, terminal 559, wiper 544, the left-hand contacts of sequence switch spring 560, wiper 575, terminal 577, conductor 225, the upper left-hand contact of sequence switch spring 224, the right-hand contact of sequence switch spring 223, the upper right-hand contact of sequence switch spring 222, and conductor 267. Due to the fact that 75 neither of the relays 310 and 351 is energized, this circuit is not completed and therefore relays 718 and 717 remain deenergized.

When the sequence switches 210 and 600 reach position 3 a circuit is closed from grounded battery through the windings of a relay 623, the lower contact of sequence switch spring 627, conductor 720, the left-hand winding of a marginal relay 719, conductor 626, conductor 620, terminal 539, wiper 540, the sequence switch contact 565, wiper 528, terminal 579, conductor 566, the upper left-hand contact of sequence switch spring 228, the lower right-hand contact of sequence switch spring 229, the upper right-hand contact of sequence switch spring 230, conductor 321, the armature and front contact of the relay 311, conductor 320, conductor 331, the windings of relay 233, and the upper back contact and armature of relay 234 to ground. Relays 233 and 623 become energized. Due to the fact, however, that the left-hand winding of relay 233 is of a relatively high resistance, the relay 719 100 remains deenergized. Upon the energization of relay 233, a shunt is removed from around the winding of relay 234 in the same manner as was described in connection with relay 219, and this relay becomes energized 105 by current flowing in the circuit extending from grounded battery through resistance 217, the right-hand contact of sequence switch spring 218, and the winding of relay 234 to ground.

Relay 623 closes a circuit from ground through the armature and back contact of relay 606, the right-hand contacts of sequence switch spring 622, the front contact and armature of relay 623, and the power magnet of sequence switch 600 to grounded battery, for moving this sequence switch out of position 3 and into position 4. Upon the opening of the lower contact of sequence switch spring 627, the circuit of relays 623 115 and 233 is broken and the latter closes a circuit from ground through its armature and back contact, the lower armature and front contact of relay 234, the right-hand back contact and armature of relay 220, the upper left-hand contact of sequence switch spring 237, and the power magnet of sequence switch 210 to grounded battery, for moving sequence switch 210 out of position 120 3 and into position 4.

District translation.

When the sequence switches 210 and 600 move through position $3\frac{1}{2}$, a circuit is prepared from ground through the left-hand winding of relay 742, conductor 741, the lower right-hand contact of sequence switch spring 619, conductor 620, terminal 539, wiper 540, the sequence switch spring 565, wiper 528, terminal 579, conductor 566, the upper contact of sequence switch spring 228, the right-hand contact of sequence switch spring 229, the upper left-hand contact of sequence switch spring 230, conductor 325, and then, due to the fact that relay 306 has not been energized, this circuit will not be completed, and thus the relay 742 arranged to control the translation remains deenergized.

Office translation.

When the sequence switches 210 and 600 reach position 4, a circuit is closed from ground through the upper armature and back contact of relay 219, the left-hand winding of relay 220, conductor 221, conductor 323, the back contact and armature of relay 322, conductor 238, the upper left-hand contact of sequence switch spring 222, the right-hand contact of sequence switch spring 223, the upper contact of sequence switch spring 224, conductor 225, terminal 577, wiper 575, the left-hand contacts of sequence switch spring 560, wiper 544, terminal 559, conductor 561, the upper contact of sequence switch spring 603, conductor 604, the left-hand winding of marginal relay 721, conductor 628, the upper left-hand contact of sequence switch spring 605, and the winding of relay 606 to grounded battery. Relays 606 and 220, due to the relatively low resistance of the circuit relay 721, become energized. The relay 721 closes a locking circuit for itself through its right-hand armature, front contact and right-hand winding in multiple with the class register relays. Relay 220 opens the shunt around relay 219 and this relay becomes energized in the above described manner. Relay 606 closes a circuit for moving the sequence switch 600 out of position 4 and into position 5, whereupon the upper left-hand contact of sequence switch spring 605 will be opened and relay 220 by releasing its armatures recloses the above-traced circuits and causes the movement of sequence switch 210 out of position 4 and into position 5.

Setting of the office brush register.

When the sequence switches 210 and 600 pass through position $4\frac{1}{2}$ a circuit is prepared from ground through the left-hand windings of a marginal relay 724 and a sensitive relay 725, conductor 726, the upper right-hand contact of sequence switch spring 624, conductor 561, terminal 559, wiper 544,

left-hand contacts of sequence switch spring 560, wiper 575, terminal 577, conductor 225, the upper left-hand contact of sequence switch spring 224, the right-hand contact of sequence switch spring 223, the lower left-hand contact of sequence switch spring 222, conductor 239, and then, due to the fact that neither of the relays 347 and 317 is energized, this circuit is not completed and relays 724 and 725 remain deenergized.

When the sequence switches reach position 5, a circuit is closed from ground through the upper armature and back contact of relay 234, the windings of relay 233, conductor 331, conductor 320, the back contact and armature of relay 328, conductor 240, the lower left-hand contact of sequence switch spring 230, the right-hand contact of sequence switch spring 229, the upper contact of sequence switch spring 228, conductor 566, terminal 579, wiper 528, sequence switch contact 565, wiper 540, terminal 539, conductor 620, conductor 626, the left-hand winding of a marginal relay 722, conductor 723, the upper contact of sequence switch spring 627, and the winding of relay 623 to grounded battery. Relays 623 and 233 become energized. Due to the fact, however, that the windings of relay 233 are of a relatively high resistance, the marginal relay 722 will not become energized. The relay 623 closes a circuit in the above described manner for driving the sequence switch 600 out of position 5 and into position 6. The relay 233 permits the energization of relay 234 and upon the opening of the circuit by sequence switch 600, relay 233 causes the movement of sequence switch 210 out of position 5 and into position 6.

Setting of the office group register.

When the sequence switch 600 and sequence switch 210 move into position $5\frac{1}{2}$ a circuit is closed from grounded battery through resistance 319, conductor 324, the front contact and armature of relay 329, conductor 242, the upper left-hand contact of sequence switch spring 241, the right-hand contact of sequence switch spring 229, the upper contact of sequence switch spring 228, conductor 566, terminal 579, wiper 528, sequence switch contact 565, wiper 540, terminal 539, conductor 620, the upper left-hand contact of sequence switch spring 619, conductor 715, the left-hand windings of a sensitive relay 714, and a marginal relay 713 to ground. Due to the fact that the resistance 319 is relatively low, both relays 714 and 713 become energized and lock up through their right-hand armatures, front contacts, and windings, and conductor 716 in multiple with the other register relays.

When the sequence switches reach position 6 a circuit is closed from ground 139

through the upper armature and back contact of relay 219, the low resistance left-hand winding of relay 220, conductor 221, conductor 323, the front contact and armature 5 of relay 313, conductor 244, the lower left-hand contact of sequence switch spring 243, the right-hand contact of sequence switch spring 223, the upper contact of sequence switch spring 224, conductor 225, terminal 10 577, wiper 575, the left-hand contact of sequence switch spring 560, wiper 544, terminal 559, conductor 561, the upper contact of sequence switch spring 603, conductor 604, the left-hand winding of a marginal relay 15 727, conductor 629, the lower left-hand contact of sequence switch spring 605, and the winding of relay 606 to grounded battery. Due to the low resistance of the left-hand winding of relay 220, relays 727, 606 and 220 20 become energized. The relay 727 locks up through its right-hand armature, front contact and winding, a multiple with relay 714. Relay 220 permits the energization of relay 219 and relay 606 causes the movement of 25 sequence switch 600 out of position 6 and into position 7. Upon the opening of the lower left-hand contact of sequence switch spring 605, relay 220 becomes deenergized and recloses the above-traced circuit and 30 drives the sequence switch 210 out of position 6 and into position 7. This sequence switch is driven out of position 7 into position 8 by a circuit extending from grounded 35 battery through the power magnet of the sequence switch, the lower right-hand contact of sequence switch spring 237, conductor 405 (Figs. 2, 3 and 4) and a contact 404 (closed in response to the actuation of any one of the keys in the stations row), to 40 ground. Since the start key is in the stations column, this circuit will be completed and sequence switch 210 will be moved into position 8.

Relay 705 being deenergized a circuit is 45 closed from ground, through the armature and back contact of this relay, conductor 728, the upper right-hand contact of sequence switch spring 609, and the power magnet of sequence switch 600 to grounded 50 battery, for moving this sequence switch out of position 7 and into position 8.

Setting of the incoming brush register.

When sequence switches 210 and 600 reach 55 position 7 $\frac{3}{4}$, a circuit is closed from ground, through the left-hand windings of marginal relay 800 and sensitive relay 801, conductor 802, the lower right-hand contact of sequence switch spring 650, conductor 561, terminal 559, wiper 544, the left-hand contacts of sequence switch spring 560, wiper 575, terminal 577, conductor 225, the upper contact of sequence switch spring 224, the right-hand contact of sequence switch spring 65 65, 223, the lower right-hand contact of se-

quence switch spring 245, conductor 246, contact 402 of the No. 9 thousands key, conductor 326 and a relatively high resistance 70 327 to grounded battery. Due to the high resistance of the circuit, only the sensitive relay 801 becomes energized. This relay closes a locking circuit for itself from ground through its inner front contact, armature and right-hand winding, a conductor 75 803 and the lower contact of sequence switch spring 621 to grounded battery.

When the two sequence switches reach position 8, a circuit is closed from grounded battery, through the winding of relay 623, the lower left-hand contact of sequence 80 switch spring 651, conductor 652, the left-hand winding of a marginal relay 804, conductor 805, conductor 806, conductor 620, terminal 539, wiper 540, sequence switch contact 565, wiper 528, terminal 579, conductor 566, the upper contact of sequence switch spring 228, the right-hand contact of sequence switch spring 229, the upper left-hand contact of sequence switch spring 247, conductor 248, contact 403 of the thousands 90 key No. 9, conductor 320, conductor 331, the windings of relay 233 and the upper back contact and armature of relay 234 to ground. The relays 623 and 233 become energized. Due to the high resistance of the circuit, the 95 relay 804 does not become energized. Relay 233 opens the shunt around the winding of relay 234 and this relay becomes energized. Relay 623 causes the movement of sequence switch 600 out of position 8 into position 9, 100 whereupon relay 223 becomes deenergized and moves sequence switch 210 out of position 8 into position 9 in the above described manner. Relay 234 becomes deenergized.

Setting of the incoming group register.

105

When the sequence switches 210 and 600 reach position 8 $\frac{3}{4}$, a circuit is prepared from ground through the left-hand winding of a sensitive relay 843, conductor 808, the lower 110 left-hand contact of sequence switch spring 653, conductor 806, conductor 620, terminal 539, wiper 540, the sequence switch contact 565, wiper 528, terminal 579, conductor 566, the upper contact of sequence switch spring 228, the right-hand contact of sequence 115 switch spring 229, the upper right-hand contact of sequence switch spring 247, conductor 249, but in view of the fact that conductor 249 is not connected to any contact of the 120 No. 9 thousands key, this circuit is not completed, and therefore relay 843 remains deenergized.

When the sequence switches reach position 9, a circuit is closed from grounded battery, 125 through the winding of relay 606, the upper left-hand contact of sequence switch spring 654, conductor 655, the left-hand winding of a marginal relay 809, conductor 810, the upper contact of sequence switch spring 603, 130

conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the upper left-hand contact of sequence switch spring 245, conductor 250, contact 400 of the hundreds key No. 8, conductor 401, conductor 330, the 10 windings of relay 220, and the upper back contact and armature of relay 219, to ground. Relays 220 and 606 become energized, and the former permits relay 219 to pull up its armature. Relay 809, however, due to the 15 high resistance of the circuit does not become energized. Relay 606 closes a circuit including the left-hand contacts of sequence switch spring 622, for driving sequence switch 600 out of position 9 and into position 10. Relay 220 becomes then deenergized and closes a circuit through the right-hand contact of sequence switch spring 232, for driving sequence switch 210 out of position 9 and into position 10.

25 *Setting of the final brush register.*

When the sequence switches reach position 9 $\frac{3}{4}$, a circuit is prepared from ground through the left-hand windings of marginal relay 811 and a sensitive relay 812, conductor 813, the lower left-hand contact of sequence switch spring 650, conductor 561, terminal 559, wiper 544, the left-hand contacts of sequence switch spring 560, wiper 575, terminal 577, conductor 225, the upper contact of sequence switch spring 224, the right hand contact of sequence switch spring 223, the lower left-hand contact of sequence switch spring 245, and conductor 251, but then, in view of the fact that the hundreds key No. 8 does not close a contact including conductor 251, this circuit is not completed and relays 811 and 812 remain deenergized.

When the sequence switches reach position 10, a circuit is closed from grounded battery, through the winding of relay 623, the upper left-hand contact of sequence switch spring 651, conductor 656, a left-hand winding of marginal relay 814, conductor 805, conductor 806, conductor 620, terminal 539, wiper 540, sequence switch contact 565, wiper 528, terminal 579, conductor 566, the upper contact of sequence switch spring 228, the right-hand contact of sequence switch spring 229, the lower right-hand contact of sequence switch spring 247, conductor 252, contact 406 of the No. 8 hundreds key, conductor 407, conductor 235, the low resistance right-hand winding of relay 233, and the 60 upper back contact and armature of relay 234 to ground. Relays 233 and 623 become energized, and the former causes the operation of relay 234. Due to the low resistance of the circuit, relay 814 becomes energized and locks up in the same manner as the other

register relays. Relay 623 closes a circuit including sequence switch spring 622, for driving sequence switch 600 out of position 10 and into position 11. Relays 233 and 623 become then deenergized and the former 70 closes a circuit to drive the sequence switch 210 out of position 10 and into position 11. Relay 234 becomes deenergized.

Setting of the final tens register.

When the sequence switches reach position 10 $\frac{3}{4}$, circuit is prepared from ground, through the left-hand windings of a marginal relay 815 and a sensitive relay 816, conductor 817, the upper right-hand contact of sequence switch spring 653, conductor 620, terminal 539, wiper 540, sequence switch contact 565, wiper 528, terminal 579, conductor 566, the upper left-hand contact of sequence switch spring 228, the right-hand contact of sequence switch spring 229, the lower left-hand contact of sequence switch spring 247, and conductor 253, but then, in view of the fact that the No. 7 tens key does not have a contact through which this conductor 253 may 90 be extended, the circuit is not completed and relays 815 and 816 remain deenergized.

When the sequence switches reach position 11, circuit is closed from grounded battery, through the winding of relay 606, the lower right-hand contact of sequence switch spring 654, conductor 818, the left-hand winding of a marginal relay 819, conductor 810, the upper contact of sequence switch spring 603, conductor 561, terminal 559, wiper 544, left-hand contacts of sequence switch spring 560, wiper 575, terminal 577, conductor 225, the upper contact of sequence switch spring 224, the right-hand contact of sequence switch spring 223, the upper right-hand contact of sequence switch spring 245, conductor 332, contact 408 of the tens key No. 7, conductor 401, conductor 330, the windings of relay 220 in series and the upper back contact and armature of relay 219 to ground. Relays 220 and 606 become energized, but, due to the high resistance of the circuit, relay 819 does not become energized. Relay 220 permits the energization of relay 219. Relay 606 closes a circuit including the left-hand contacts of sequence switch spring 622 for driving sequence switch 600 out of position 11 and into position 12, whereupon relays 220 and 606 become deenergized, and the former moves the sequence switch 210 out of position 11 and into position 12 by a circuit including the upper right-hand contact of sequence switch spring 232. Relay 219 becomes deenergized.

Final tens translation.

When the sequence switches 600 and 210 reach position 11 $\frac{3}{4}$, a circuit is prepared from ground, through the right-hand winding of a relay 832, a conductor 833, the lower 130

- contact of sequence switch spring 603, conductor 561, terminal 559, wiper 544, the left-hand contacts of sequence switch spring 560, wiper 575, terminal 577, conductor 225, the 5 upper contact of sequence switch spring 224, the right-hand contact of sequence switch spring 223, the upper left-hand contact of sequence switch spring 243, and conductor 336, contact 418 of the No. 7 tens key, conductor 324 and the low resistance 319 to grounded battery. The relay 832 becomes energized, and locks up in the same manner as the register relays.

15 *Final units translation.*

- When the sequence switches reach position 12, a circuit is closed from grounded battery through the winding of relay 623, the upper right-hand contact of sequence switch spring 651, conductor 820, the left-hand winding of a marginal relay 821, conductor 806, conductor 620, terminal 539, wiper 540, sequence switch contact 565, wiper 528, terminal 579, conductor 566, the 20 upper contact of sequence switch spring 228, the right-hand contact of sequence switch spring 229, the lower right-hand contact of sequence switch spring 241, conductor 333, contact 409 of units key No. 6, conductor 407, conductor 235, the low resistance right-hand winding of relay 233 and the upper back contact and armature of relay 234, to ground. Relays 233 and 623 become energized and the former permits 25 relay 234 to operate. Due to the low resistance of the circuit, relay 821 also becomes energized and locks up in the same manner as the other register relays. Relay 623 closes a circuit including the right-hand contacts 30 of sequence switch spring 622, for driving sequence switch 600 out of position 12 and into position 13. Relays 623 and 233 become then deenergized and the latter closes a circuit to move the sequence switch 210 out of 35 position 12 and into position 13.

Setting of the final units register.

- When the sequence switches reach position 12³, a circuit is closed from ground, through 50 the left-hand windings of a marginal relay 822 and a sensitive relay 823, conductor 824, the lower right-hand contact of sequence switch spring 653, conductor 620, terminal 539, wiper 540, sequence switch contact 565, wiper 528, terminal 579, conductor 566, the 55 upper contact of sequence switch spring 228, the right-hand contact of sequence switch spring 229, the upper right-hand contact of sequence switch spring 241, conductor 254, contact 410 of the No. 6 units key, conductor 324, and the low resistance 319 to grounded battery. Due to the low resistance of the 60 circuit, both relays 822 and 823 become energized and lock up through their right-hand windings and conductor 803.

When the sequence switches reach position 13, a circuit is closed from grounded battery, through the winding of relay 606, the lower left-hand contact of sequence switch spring 654, conductor 825, the left-hand winding of a marginal relay 826, conductor 810, the upper contact of sequence switch spring 603, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the upper right-hand contact of sequence switch spring 243, conductor 255, contact 411 of units key No. 6, conductor 323, conductor 221, the left-hand winding of relay 220 and the upper back contact and armature of relay 219 to ground. Relays 220 and 606 become energized and the former causes the operation of relay 219. Due to the low resistance of the circuit, relay 826 becomes energized and locks up. Relay 606 closes a circuit including the left-hand contacts of sequence switch spring 622, for driving sequence switch 600 out of position 13 and into position 14, whereupon relays 606 and 220 become deenergized and the latter moves the sequence switch 210 out of position 13 and into position 14. Relay 219 becomes then deenergized.

Setting of the stations register.

When the sequence switches reach position 13³, a circuit is closed from ground, through the left-hand windings of a marginal relay 827, and a sensitive relay 828, conductor 829, the upper right-hand contact of sequence switch spring 650, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the lower right-hand contact of sequence switch spring 243, conductor 334, contact 416 of the start key 414, conductor 338, and the low resistance 339 to grounded battery. Due to the low resistance of this circuit both 115 relays 827 and 828 become energized and lock up through their right-hand windings and conductor 803.

When the sequence switches reach position 14, a circuit is closed from grounded battery 120 through the winding of relay 623, the lower right-hand contact of sequence switch spring 651, conductor 880, the left-hand winding of marginal relay 831, conductor 805, conductor 806, conductor 620, terminal 539, wiper 540, sequence switch contact 565, wiper 528, terminal 579, conductor 566, the upper contact of sequence switch spring 228, the right-hand contact of sequence switch spring 229, the lower left-hand contact of 130

- sequence switch spring 241, conductor 335, contact 415 of the start key 414, conductor 320, conductor 331, the windings of relay 233 and the upper back contact and armature 5 of relay 234 to ground. Relays 233 and 623 become energized, but due to the high resistance of the circuit relay 831 is not energized. Relay 233 permits relay 234 to pull up its armatures. Relay 623 closes a circuit including the right-hand contacts of sequence switch springs 622, for driving sequence switch 600 out of position 14 and into position 15, whereupon relay 233 becomes deenergized and causes the movement of sequence switch 210 out of position 14 and into position 15.

Restoration of the keyboard and its controlling apparatus.

- 20 When sequence switch 210 reaches position 15, a circuit is closed from ground through the upper armature and back contact of relay 219, the windings of relay 220, conductors 330 and 401, contact 400 of the hundreds key No. 8, conductor 250, the upper left-hand contact of sequence switch spring 245, the left-hand contact of sequence switch spring 223, conductors 337 and 338, and the resistance 339 to grounded battery.
- 25 Relay 220 becomes energized, locks up through its left hand front contact, and by opening the shunt around relay 219, permits this relay to become energized. Another circuit is closed from ground through the upper armature and back contact of relay 234, the windings of relay 233, conductors 331 and 320, contact 403 of the thousands key No. 9, conductor 248, the upper left-hand contact of sequence switch spring 247, 30 the left-hand contact of sequence switch spring 229, conductors 340 and 324, and resistance 319 to grounded battery. The energized condition of relays 220 and 233 depends also on the closure of the following 35 circuits: 1, from ground, through the upper armature and back contacts of relay 219, the left-hand winding of relay 220, conductor 221, conductor 323, contact 408 of the tens key No. 7, conductor 332, the upper right-hand contact of sequence switch spring 40 245, the left-hand contact of sequence switch spring 223, conductor 337, and the low resistance 339 to grounded battery; and 2, from ground through the upper armature 45 and back contact of relay 234, the right-hand winding of relay 233, conductor 235, conductor 407, the contact 409 of the No. 6 units key, conductor 333, the lower right-hand contact of sequence switch spring 241, 50 the left-hand contact of sequence switch spring 220, conductor 340, and the low resistance 319 to grounded battery.
- 55 Relay 233 becomes energized and closes a circuit from ground, through the upper armature and front contact of relay 219, se-

quence switch spring 258, the left-hand front contact and armature of relay 233, and the power magnet of sequence switch 210 to grounded battery. The sequence switch is moved into position 16, whereupon a circuit 70 is closed from ground, through sequence switch contact 259, conductor 341 and the windings of all the magnets 342 in multiple to grounded battery. The magnets 342 restore the depressed keys to normal and when 75 all the actuated keys are restored, all the relays that were held up through contacts of the keys become deenergized. Relay 219 being maintained energized in position 16 of sequence switch 210, a circuit is closed 80 from ground through the left-hand back contact of relay 220, the lower armature and front contact of relay 219, the left-hand contact of sequence switch spring 232, the armature and back contact of relay 214, conductor 85 343, the right-hand armature and back contact of relay 344, conductor 345, the left-hand back contact and armature of relay 233 and the power magnet of sequence switch 210 to grounded battery. The sequence switch 210 90 is moved out of position 16 and into position 18. The magnets 342 become deenergized.

The operator, noticing the restoration of the keys, depresses her listening-out key 260, 95 closing thus a circuit through the lower left-hand contact of sequence switch spring 201, for driving sequence switch 202 out of position 7 and into position 11, which is the listening-out position.

Should the operator desire to listen in, she would depress the listening-in key 261, closing thus a circuit from the upper left-hand contact of sequence switch spring 201, for driving sequence switch 202 out of position 11 100 and into position 1, from which position the sequence switch would be driven into position 7 by the above traced circuit closed through the armature and front contact of relay 103, and the lower right-hand contact 105 of sequence switch spring 201.

When the sequence switch 202 moves out of position 7, it opens in contact 208 the locking circuit of relay 211. This relay closes a circuit from ground, through its left-hand 115 armature and back contact, and the lower left-hand contact of sequence switch spring 237, for driving sequence switch 210 out of position 18 into position 1.

The keyboard and its controlling apparatus is now restored to normal and ready for controlling the setting of another sender and set of registers.

District group selection.

As soon as sequence switch 600 reaches position 8, a fundamental circuit is completed from ground through the lower right-hand contact of sequence switch spring 630, the upper contact of sequence switch spring 631, 125 130

the windings of stepping relay 632, the right-hand back contact and armature of relay 633, the left-hand contact of sequence switch spring 615, conductor 564, terminal 557, 5 wiper 538, sequence switch contact 563, wiper 576, terminal 578, conductor 227, the upper contact of sequence switch spring 226, the lower contact of sequence switch spring 266, conductor 116, the lower left-hand contact 10 of sequence switch spring 115 and the winding of relay 114 to grounded battery. Relay 114 becomes energized and closes a circuit from ground through its left-hand front contact, the upper right-hand contact of sequence switch spring 117 and the power magnet 15 of sequence switch 108 to grounded battery, whereupon the sequence switch 108 is driven out of position 2 into position 3. The relay 114 is then locked up through its right-hand front contact and armature, and the lower right-hand contact of sequence switch spring 115.

Relay 632, upon energization, closes a circuit from ground through its armature and front contact and the winding of stepping magnet 634 to grounded battery.

In position 3 of sequence switch 108, a circuit is closed from grounded battery, through the winding of magnet 119, the upper contact of sequence switch spring 120, and the left-hand front contact and armature of relay 114 to ground. Magnet 119 becomes energized and by attracting its armature presses brush rod 121 of the district selector 35 against the roller 123 continuously rotating in the direction of the arrow.

Upon the energization of relay 113^a a circuit was closed from ground through the front contact and armature of this relay, the 40 winding of a trip magnet 128^a to grounded battery. Magnet 128^a by attracting its armature rotated a tripping rod 129, moving thus a tripping finger 130 into the path of a catch 131 provided on the cam 127 by 45 means of which the wipers of set 124 are separated. Before the wipers can engage the lowermost terminals of a bank 126, tripping finger 130, being in engagement with catch 131, causes the removal of cam 127 50 from between the wipers, allowing the wipers to contact with the terminals of bank 126. It will be seen that if, instead of office key B, the office key A is depressed, then the relay 113 becomes energized and causes 55 the tripping magnet 128 to trip another set of wipers on brush rod 121. In the same manner, depending on the depression of a certain office key or a certain tandem hundreds key, a certain one of the relays 113 60 will be energized to cause the tripping of one of the five district wiper sets. When the wipers of set 124 reach the lowermost terminals of bank 126, a commutator brush 125 carried by brush rod 121 is in engagement 65 with a conducting segment 133. A

circuit is thus closed from ground, brush 125, conducting segment 133, the right-hand contacts of sequence switch spring 115, the right-hand armature, front contact and winding of relay 114 to grounded battery. 70 Due to the closure of this shunt path, the stepping relay 632, which is connected in series with relay 114, becomes deenergized and permits magnet 634 to move the sender wipers 635, 636 by one step in the direction 75 indicated by the arrow. During the further travel of the district selector 122, brush 125 engages an insulating segment 134 and the shunt is removed from the winding of the relay 114, and relay 632 again becomes energized and causes the energization of magnet 634. 80 The operation of the selector 122 continues in the same manner and the relay 632 operates in response to each step taken by the selector. As above stated, in response to 85 the depression of office key B, the district group register is set to arrest the sender when the wiper 635 engages the terminal No. 3. The translation relay 742 serves to determine whether the sender should be arrested with the wiper 635 on terminal No. 90 3 in section C or D. If the relay 742 is energized, then, upon the engagement by wiper 635 of the terminal No. 3 in section C, a circuit is established from grounded battery, 95 through the winding of relay 633, conductor 637, the left-hand contact of sequence switch spring 638, conductor 639, the upper left-hand contact of sequence switch spring 640, conductor 641, the upper contact of sequence 100 switch spring 729, the outer armatures and back contacts of relays 717 and 719, the No. 3 terminal in section C, wipers 635 and 636, conductor 642, the left-hand front contact and armature of relay 742, the upper left-hand contact of sequence switch spring 730, conductor 731, the upper left-hand contact of sequence switch spring 643, conductor 644, the left-hand contact of sequence switch 105 spring 645, the back contact and armature of magnet 634, and sequence switch spring 646, to ground. In view of the fact that relay 742 was not energized during the setting of the registers, the relay 633 will not become energized when the wiper 635 engages 110 the terminal No. 3 in section C, and thus the sender wipers are permitted to rotate, under the control of the selector 122, by nine steps. Upon the ninth deenergization of magnet 634, the wiper 635 engages 115 the terminal No. 3 in section D, and wiper 636 engages the terminals connected to conductor 657, and a circuit is closed from grounded battery, through the winding of relay 633, conductor 637, the lower left-hand contact of sequence switch spring 638, conductor 639, the upper left-hand contact of sequence switch spring 640, conductor 641, the upper contact of sequence switch spring 120 729, the outer armatures and back contacts 125 130

of relays 717 and 719, the terminal No. 3 in section D, wipers 635 and 636, conductor 657, the back contact and armature of magnet 634 and sequence switch contact 646 to ground. Relay 633 becomes energized and attracts its armature, opening at its back contact the fundamental circuit, causing thus the deenergization of relay 114, which, by opening its left-hand front contact, causes the deenergization of magnet 119. The wipers are thereupon arrested in contact with the lowermost terminals of the ninth group of trunks leading to an incoming selector. For the purpose of insuring the centering of the district selector wipers, the relay 114 is maintained energized as long as the brush 125 is in engagement with the conducting segment 133. Relay 633 closes a circuit from grounded battery, through its left-hand armature and front contact, the upper left-hand contact of sequence switch spring 647, and the power magnet of sequence switch 613 to grounded battery, causing thus the movement of the sequence switch 613 out of position 2 into position 3. The sender being in an off-normal position, the contact 648 is closed. As soon as the sequence switch 613 reaches position 3 it closes a circuit from grounded battery through the winding of magnet 634, sequence switch contact 649, off-normal contact 648, the back contact and armature of magnet 634, the back contact and armature of relay 633, to ground. Magnet 634 by interrupting its own circuit causes the stepping of the wipers 635 and 636 in a forward direction until they reach their normal position, when, by opening the above traced circuit at contact 648, they cause the deenergization of magnet 634. Upon the permanent deenergization of magnet 634, a circuit is closed from ground, through the left-hand armatures and back contacts of relay 633 and magnet 634, conductor 657, wipers 635 and 636, the lower left-hand contact of sequence switch spring 647, and the power magnet of sequence switch 613 to grounded battery, whereupon the sequence switch is moved out of position 3 into position 4. Upon deenergization, relay 114 closes a circuit from ground, through its left-hand armature and back contact, left-hand contact of spring 117 and the power magnet of sequence switch 108 to grounded battery, for moving this sequence switch out of position 3 and into position 6. A circuit is now closed from grounded battery, through the left-hand winding of a test relay 135 and the lower left-hand contact of sequence switch spring 136 to ground. Relay 135 closes a circuit from ground through the lower right-hand contact of sequence switch spring 117, and the power magnet of sequence switch 108 to grounded battery, for moving the sequence switch 108 out of position 6 and into position

7. Supposing that the first trunk of the selected group is busy, a ground is connected to a test terminal 137 of this trunk in a manner to be hereinafter described. A circuit will thus be closed from ground through terminal 137, wiper 138, the right-hand armature and front contact of relay 135, and the right-hand winding of relay 135 to grounded battery, for maintaining this relay energized. Relay 135 being energized, a circuit is closed from ground, through the left-hand armature of this relay, the lower contact of sequence switch spring 120 and the winding of up-drive magnet 119 to grounded battery. Magnet 119 causes the wipers of selector 122 to engage the terminals of the next trunk in the group. If this trunk is idle, the relay 135 becomes deenergized, and connects ground through the upper left-hand contact of sequence switch spring 136, the right-hand back contact and armature of relay 135, and wiper 138 to the multiples of test terminal 139, preventing thus the seizure of this trunk by another selector 122. A circuit is also completed from grounded battery, power magnet of sequence switch 108, lower left-hand contact of spring 117, left-hand armature and back contact of relay 135 to ground, for moving this sequence switch out of position 7 and into position 11.

Office brush selection.

As soon as the trunk 143, 144, 145 is seized, the fundamental circuit is again established, but now extends from grounded battery, through the winding of a relay 146 (Fig. 9), the lower contact of sequence switch spring 147, conductor 143, terminal 140, wiper 141, the right-hand contact of sequence switch spring 142, and then through the same path as above traced for relay 114, to ground at sequence switch spring 630. Relays 146 and 632 become energized. Relay 632 causes the energization of magnet 634, and relay 146 closes a locking circuit for itself through its right-hand front contact and armature and the upper contact of sequence switch spring 147. Relay 146 also closes a circuit from ground through its left-hand armature and front contact, the contact of sequence switch spring 148 and the winding of a relay 149, to grounded battery. Relay 149 becomes energized and closes a locking circuit for itself from grounded battery through its winding, left-hand front contact and armature, a resistance 150, trunk conductor 145, terminal 139, wiper 138, the right-hand armature and back contact of relay 135, and the upper left-hand contact of sequence switch spring 136 to ground. Upon energization, relay 149 closes a circuit from ground through its right-hand armature and front contact, the lower right-hand contact of sequence switch spring 151, and the power magnet 130

of sequence switch 152 to grounded battery. The sequence switch is moved out of position 1, and under the control of its normal contact 153, into position 2. A circuit is now closed from grounded battery, through the winding of a magnet 154, the lower contact of sequence switch spring 155, and the left-hand front contact and armature of relay 146, to ground. Magnet 154, by 5 attracting its armature, presses a brush rod 156 of the office selector 157 against a roller 158 constantly rotating in the direction indicated by the arrow. The wiper and the commutator brush carried by the brush rod 156 10 will thus be moved in an upward direction. As soon as a commutator brush 159 engages conducting segment 160, a shunt is closed from ground through conducting segment 160, the lower contact of sequence switch 20 spring 161, and the right-hand armature, front contact and winding of relay 146 to grounded battery. Due to the closure of this shunt, the relay 632 becomes deenergized and permits the deenergization of magnet 25 634, whereupon the wipers of the sender will be rotated by one step. When brush 159 engages the first one of the insulated segments 162, the shunt is removed from the winding of relay 146; therefore, the relay 632 becomes again energized and causes, in turn, the energization of magnet 634. When the brush 159 leaves the first insulated segment 162 and engages again the conducting plate 160, relay 632 is 30 shunted, causing the deenergization of magnet 634. As soon as the sender wiper 635 engages terminal No. 3 in section C, which happens in response to the fourth shunting out of relay 632 by the selector 157, 35 a circuit is closed from grounded battery, through the winding of relay 633, conductor 637, left-hand contact of sequence switch spring 638, conductor 639, the upper right-hand contact of sequence switch spring 658, conductor 732, the upper right-hand contact of sequence switch spring 733, the outer armatures and back contacts of relays 725 and 722, the No. 3 terminal of the sender, wipers 635, 636, conductor 642, conductor 40 669, the lower left-hand contact of sequence switch spring 643, conductor 644, left-hand contact of sequence switch spring 645, the back contact and armature of magnet 634, sequence switch contact 646 to ground. 45 Relay 633 opens in its right-hand back contact the fundamental circuit, and closes a circuit from ground, through its left-hand armature and front contact, the upper left-hand contact of sequence switch spring 647, and the power magnet of sequence switch 613 to grounded battery, causing the movement of sequence switch 613 out of position 50 4 and into position 5. In response to the opening of the fundamental circuit, relays 632 and 146 become deenergized. Relay 146 55 closes a circuit from ground, through its left-hand armature and back contact, upper left-hand contact of sequence switch spring 151 and the power magnet of sequence switch 152 to ground, whereupon the sequence 60 switch 152 moves out of position 2 and into position 3. In response to the deenergization of relay 146 the circuit of the up-drive magnet 154 is opened and thus the selector 157 arrested in its upward travel. When the sequence switch 152 reaches position 3, a circuit is closed from ground, through sequence switch contact 163 and the winding of a trip magnet 164 to grounded battery. The operation of magnet 164 trips the fourth 65 set of brushes and allows them to engage the terminals in the bank. 70 In position 5 of sequence switch 613 a circuit is closed from grounded battery, through the winding of magnet 634, sequence 75 switch contact 649, off-normal contact 648 of the sender, the left-hand back contact and armature of magnet 634, and the left-hand back contact and armature of relay 633 to ground. Magnet 634 by interrupting its 80 own circuit causes the restoration of the sender to normal, whereupon its circuit is interrupted in contact 648. Upon deenergization, magnet 634 closes a circuit from ground, through the left-hand armature and back contact of relay 633, armature and back contact of magnet 634, conductor 657, sender wipers 635, 636, the lower left-hand contact of sequence switch spring 647, the power magnet of sequence switch 613 to grounded 85 battery, for moving this sequence switch out of position 5 and into position 6. 90 95 *Office group selection.* The fundamental circuit is now again 100 established through the upper contact of sequence switch spring 631. Relays 632 and 146 become energized. Relay 632 causes the energization of magnet 634 and the relay 146 the closure of a circuit from ground, 105 through its left-hand armature and front contact, the lower left-hand contact of sequence switch spring 165, the power magnet of sequence switch 152 to grounded battery. The sequence switch is moved into position 110 4, whereupon the circuit of magnet 154 is again established. When the sequence switch 152 moves out of position 3 the relay 146 locks up its winding in the same manner as above described. In response to the energization of magnet 154, the brush rod 156 is again caused to travel in an upward direction. When the brush 159 engages the conducting plate 166, it closes a shunt from ground, through this plate 166, 115 the upper right-hand contact of sequence switch spring 161, and the right-hand armature and front contact of relay 146 to the winding of this relay. The stepping relay 632 is shunted out in the same manner 120 125 130

as above described and permits magnet 634 to move the brushes of the sender. Every time brush 159 engages one of the insulated segments 167, the shunt which is closed 5 through conducting plate 166, is removed from the winding of relay 146, and thus the relay 632 controls, through the agency of the magnet 634, the stepping of the sender. As soon as the wiper 635 engages 10 the terminal No. 0 in section C, upon the deenergization of magnet 634, a circuit is closed from grounded battery, through the winding of relay 633, conductor 637, left-hand contact of sequence switch spring 638, conductor 639, lower right-hand contact of sequence switch spring 640, conductor 734, the upper contact of sequence switch spring 735, the outer armature and front contact of relay 714, middle armature and front 15 contact of relay 727, and the middle armature and front contact of relay 713 to the No. 0 terminal of the sender, wipers 635 and 636 of the sender, conductor 642, the left-hand front contact and armature of relay 721, 20 the lower contact of sequence switch spring 736, conductor 743, the lower right-hand contact of sequence switch spring 643, conductor 644, left-hand contact of sequence switch spring 645, the back contact and armature of magnet 634, sequence switch 25 spring 646 to ground. Relay 633 becomes energized and opens in its left-hand front contact the fundamental circuit. Relay 146 becomes deenergized and opens the circuit of magnet 154, whereupon the selector is arrested. Relay 146 closes a circuit from 30 ground, through its left-hand armature and back contact, upper contact of sequence switch spring 151, and the power magnet of sequence switch 152 to grounded battery, for driving this sequence switch out of 35 position 4 and into position 7.

Relay 633 closes a circuit from ground, through its left-hand armature and front 40 contact, the upper left-hand contact of sequence switch spring 647, and the power magnet of sequence switch 613 to grounded battery, for moving this sequence switch out of position 6 and into position 7. A 45 circuit is then closed from grounded battery through the winding of magnet 634, sequence switch contact 649, off-normal contact 648, back contact and armature of magnet 634, and back contact and armature 50 of relay 633 to ground. The magnet 634 causes the restoration of the sender in the same manner as above described, and when the sender reaches its normal position, magnet 634 becomes permanently deenergized. A circuit is now closed from 55 grounded battery, through the power magnet of sequence switch 613, the lower right-hand contact of sequence switch spring 647, sequence switch contact 659, sender wipers 636 and 635, conductor 657, and the left-

hand contacts and armatures of magnet 634 and relay 633 to ground. The sequence switch 613 is thus moved out of position 7 and into position 8.

In view of the fact that the class-register sequence switch is in position 1, indicating that the tandem hundreds, tens and units impulses must not be sent out, the sender sequence switch is immediately moved out of position 8 and into position 14. This is 75 accomplished in the following manner: As soon as the sequence switch 613 reaches position 8, a circuit is closed from grounded battery, through the winding of relay 633, conductor 637, the left-hand contact of sequence switch spring 638, conductor 639, the lower left-hand contact of sequence switch spring 658 and the contact of sequence switch spring 738, to ground. Relay 633 becomes energized and closes a circuit from ground through its left-hand armature and front contact, the upper left-hand contact of sequence switch spring 647, and the power magnet of sequence switch 613, to grounded battery, for moving this sequence switch 90 out of position 8 and into position 9. By opening its right-hand back contact, the relay 633 prevents the reestablishment of the fundamental circuit and thus the receipt of impulses by stepping relay 632. 95

When the sequence switch 613 reaches position 9 the relay 633 becomes deenergized, and a circuit is closed from grounded battery, through the power magnet of sequence switch 613, the lower left-hand contact of sequence switch spring 647, the sender wipers 636 and 635, conductor 657, the back contact and armature of magnet 634, and the left-hand back contact and armature of relay 633, to ground. The sequence switch 613 100 moves into position 10.

A circuit is then closed from grounded battery, through the winding of relay 633, conductor 637, the left-hand contact of sequence switch spring 638, conductor 639, the lower left-hand contact of sequence switch spring 658 and sequence switch spring 738, to ground. Relay 633 becomes energized and moves the sequence switch 613 out of position 10 and into position 11 in the same 110 manner as above described, whereupon relay 633 becomes deenergized and reestablishes the above traced circuit through the lower left-hand contact of sequence switch spring 647, for moving the sequence switch 613 into 115 position 12. In this position of the sequence switch 613 the mentioned circuit through sequence switch spring 738 is again closed for driving the sequence switch 613 out of position 12 and into position 13, whereupon 120 the circuit through the lower left-hand contact of sequence switch spring 647 is closed to drive the sequence switch out of position 13 and into position 14.

The lower left-hand contact of sequence 130

switch spring 658 being now open, relay 633 cannot become reenergized.

When the sequence switch 152 reaches position 7 a circuit is closed from ground, 5 through the lower left-hand contact of sequence switch spring 168, and the left-hand winding of test relay 169 to grounded battery. This relay becomes energized, and if the test terminal of the trunk selected is 10 busy, closes a locking circuit for itself from grounded battery, through its right-hand winding, front contact of armature of test relay 169, wiper 170 and its terminal 171 to ground. Upon the energization of relay 169 15 a circuit is closed from ground, through the left-hand armature and front contact of this relay, upper right-hand contact of sequence switch spring 165, and the power magnet of sequence switch 152 to grounded battery, 20 for moving it out of position 7 and into position 9. In position 9 of the sequence switch, relay 169 closes a circuit from ground, through the left-hand armature and front contact of this relay, upper contact of sequence switch spring 155, the winding of magnet 152 to grounded battery, and under the control of this magnet the selector 157 is caused to continue in its upward travel. Supposing that the next terminal to be 25 countered is 172 and that the trunk terminating therein is idle, the locking circuit for relay 169 is opened. This relay becomes deenergized and opens in its left-hand front contact the circuit of magnet 154, and closes 30 a circuit from ground, through its left-hand armature and back contact, the upper left-hand contact of sequence switch spring 165, and the power magnet of sequence switch 152 to grounded battery, for moving it out 35 of position 9 and into position 16. A circuit is now closed from ground, through the upper left-hand contact of sequence switch spring 168, and the test wiper 171 to the multiples of test terminal 172, preventing 40 thus the seizure of this trunk by other office selector switches.

Incoming brush selection.

As soon as the trunk 900, 901, 902 is seized 50 and the sequence switch 613 reaches position 14, the fundamental circuit is again closed, but extends now from grounded battery, through the winding of a relay 903, the lower left-hand contact of sequence switch spring 55 904, the upper left-hand contact of sequence switch spring 905, resistance 906, trunk conductor 900, wiper 173, sequence switch contact 174, conductor 143, wiper 141, the right-hand contact of sequence switch spring 142, conductor 116, the lower contact of sequence switch spring 266, the upper contact of sequence switch spring 226, conductor 227, terminal 578, wiper 576, sequence switch contact 563, wiper 538, terminal 557, conductor 60 564, the left-hand contact of sequence switch 65 spring 615, the right-hand armature and back contact of relay 633, the windings of relay 632, the lower contact of sequence switch spring 631, conductor 620, terminal 539, wiper 540, sequence switch contact 565, 70 wiper 528, terminal 579, conductor 566, the upper contact of sequence switch spring 228, the lower contact of sequence switch spring 269, conductor 268, the right-hand contact of sequence switch spring 177, wiper 178, 75 conductor 144, sequence switch contact 175, wiper 176, conductor 901, the left-hand contact of sequence switch spring 907, and resistance 908, to ground. Relays 632 and 903 become energized. Relay 632 causes the energization of magnet 634. Relay 903 closes a locking circuit for itself, including its inner armature and front contact and the lower right-hand contact of sequence switch 80 85 spring 904. This relay also closes a circuit from ground, through the upper contact of sequence switch spring 909, the outer armature and front contact of relay 903, the lower left-hand contact of sequence switch spring 910, and the winding of a relay 911 90 to grounded battery. Relay 911 closes a locking circuit for itself, including its left-hand front contact and armature, a resistance 952, the trunk conductor 902, terminal 172, wiper 170, the right-hand armature and back contact of relay 169, and the upper left-hand contact of sequence switch spring 168 to ground. Relay 911 closes a circuit from ground, through its right-hand armature and front contact, the lower left-hand 100 and upper right-hand contacts of sequence switch spring 912, and the power magnet of sequence switch 913 to grounded battery. The sequence switch is moved out of position 1, and under the control of its normal contact 914, into position 2. A circuit is now closed from grounded battery, through the winding of a magnet 915, the lower right-hand contact of sequence switch spring 910, the outer front contact and armature of relay 903, and the upper contact of sequence switch spring 909 to ground. Magnet 915, 105 by attracting its armature, presses a brush rod 916 of the incoming selector 917 against a roller 918 constantly rotating in the direction indicated by the arrow, causing thus the upward movement of the wipers and brushes of the selector 917.

As soon as a brush 919 engages a conducting plate 920, a ground is connected through the lower contact of sequence switch spring 921, brush 919, conducting plate 920, the upper left-hand and lower right-hand contacts of sequence switch spring 904, to the winding of relay 903. The sender stepping 120 relay 632 is now shunted out and upon its de-energization, causes the deenergization of magnet 634, whereupon the wipers of the sender are rotated by one step. When the brush 919 leaves the conducting plate and 125 130

engages the first one of the insulated segments 922, the shunt is removed from the winding of relay 632 and the stepping relay 632 is permitted to reenergize. The sender 5 stepping relay will be thus shunted out and permitted to reenergize in response to the successive engagement of the conducting segment 920, and insulated segments 922 by brush 919. Under the control of relay 632, 10 the magnet 634 is operated to stop the wipers of the sender.

Upon the fifth deenergization of magnet 634 and as soon as wiper 635 engages the terminal No. 4 of section C, a circuit is closed 15 from grounded battery, through the winding of relay 633, conductor 637, the left-hand contact of sequence switch spring 638, the upper right-hand contact of sequence switch spring 661, conductor 834, the outer armature and front contact of relay 801, the middle armature and back contact of relay 804, and the outer armature and back contact of 20 relay 800, and then to terminal No. 4 of the sender, wipers 635 and 636, conductor 642, the lower left-hand contact of sequence 25 switch spring 643, conductor 644, the left-hand contact of sequence switch spring 645, the back contact and armature of magnet 634, and sequence switch contact 646 to 30 ground. Relay 633 becomes energized, opens the fundamental circuit, and causes the movement of sequence switch 613 out of position 35 14 into position 15, whereupon the magnet 634 is operated by a circuit closed through the contacts 648 and 649, for moving the sender to its normal position. When the sender reaches its normal position, the magnet 634 becomes deenergized and closes a 40 circuit for the sequence switch 613 to drive it out of position 15 and into position 16.

Upon the opening of the fundamental circuit, relay 903 becomes deenergized and closes a circuit from ground through the upper contact of sequence switch spring 909, 45 its outer armature and back contact, the left-hand armature and back contact of a relay 923, the right-hand contacts of sequence switch spring 912, and the power magnet of sequence switch 913 to grounded battery, for 50 driving this sequence switch out of position 2 and into position 3. Magnet 915 is now temporarily deenergized and the selector arrested with the wipers below the lowest row of contacts in the respective panels.

55 A circuit is now closed from ground through the right-hand contacts of sequence switch spring 927 and the winding of trip magnet 926 to ground and battery. The trip magnet becomes energized and remains 60 energized until the sequence switch 913 is moved out of position 4. Upon the initiation of the group selecting operation, to be hereinafter described, the wipers 925 will be tripped to permit their engaging the contacts of the fifth panel.

Incoming group selection.

Sequence switch 613 being in position 16 and sequence switch 913 in position 3, the fundamental circuit traced in connection 70 with the incoming brush selection is again closed. Relays 632 and 903 become energized. The energization of relay 632 causes the energization of magnet 634. Relay 903 recloses the above traced locking circuit for 75 itself and closes a circuit from ground through the upper contact and sequence switch spring 909, outer armature and front contact of relay 903, the contacts of sequence switch spring 924 and the power 80 magnet of sequence switch 913 to grounded battery. The sequence switch 913 is moved out of position 3 and into position 4. As soon as this sequence switch reaches position 4 the lower contact of sequence switch 85 spring 910 is again closed, whereupon magnet 915 becomes energized and causes the incoming selector to continue its upward travel.

As soon as brush 934 engages contacting 90 plate 935, ground is connected through the lower contact of sequence switch spring 921, brush 934, contacting plate 935, the right-hand contacts of sequence switch spring 904 and the inner armature and front contact 95 of relay 903 to the winding of this relay. The sender stepping relay 632 is now shunted out and upon deenergization causes the deenergization of magnet 634, whereupon the wipers of the sender are rotated by one 100 step. When the brush 934 leaves contacting plate 935 and engages the first one of the insulated segments 936, the shunt is removed from the winding of relay 632 and this relay is permitted to reenergize. The 105 sender stepping relay will thus be shunted out and permitted to reenergize in response to the successive engagement of the conducting segment 935 and the insulated segments 936 by brush 934. Under the control of 110 relay 632 the magnet 634 is operated to step the wipers of the sender. Upon the fourth deenergization of magnet 634 and as soon as wiper 635 engages terminal 3 of section C, a circuit is closed from grounded 115 battery through the winding of relay 633, conductor 637, the lower left-hand contact of sequence switch spring 638, conductor 639, the lower left-hand contact of sequence switch spring 661, conductor 836, the outer 120 armatures and back contacts of relays 843 and 809, sender wipers 635 and 636, conductor 642, the lower left-hand contact of sequence switch 643, conductor 644, the left-hand contact of sequence switch 125 spring 645, contact and armature of magnet 634, sequence switch spring 646 to ground. Relay 633 becomes energized, opens the fundamental circuit and causes the movement of sequence switch 613 out 130

of position 16 and into position 17. The magnet 634 becomes again energized by current flowing in a circuit closed through the contacts 648 and 649 of the sequence switch 5 for moving the sender to its normal position. When the sender reaches its normal position magnet 634 becomes deenergized and closes a circuit for sequence switch 613 to drive it out of position 17 and into position 18.

Upon the opening of the fundamental circuit relay 903 becomes deenergized and closes a circuit from ground through the upper contact of sequence switch spring 909, outer armature and back contact of relay 903, left-hand armature and back contact of relay 923, the right-hand contacts of sequence switch spring 912 and the power magnet of sequence switch 913 to grounded 20 battery. The sequence switch 913 is moved out of position 4 and into position 5.

In position 5 of the sequence switch 913, a circuit is closed from grounded battery, through the left-hand winding of relay 923, 25 and upper contacts of sequence switch spring 927, to ground. Relay 923 closes a circuit from ground through the upper contact of sequence switch spring 909, the outer armature and back contact of relay 903, the left-hand armature and front contact of relay 923, the left-hand contacts of sequence switch spring 924, and the power magnet of sequence switch 913, to grounded battery, for moving this sequence switch out of position 30 5 into position 6. In this position of the sequence switch, the above traced circuit of relay 923 is opened in the upper right-hand contact of sequence switch spring 927. If, however, the first trunk in the selected group 40 is busy, then, as will be hereinafter set forth, ground is connected to the test terminal of such trunk and, therefore, the relay 923 remains energized by current flowing from grounded battery, through its right-hand 45 winding, the left-hand contact of sequence switch spring 931, the right-hand front contact and armature of relay 923, and test wiper 953 to ground. Independently of this circuit, relay 923 is maintained energized as long as a commutator brush 928 50 engages conducting segments of commutator 929, a circuit being closed from ground, through the lower right-hand contact of sequence switch spring 921, brush 928, conducting segment of commutator 929, the left-hand contacts of sequence switch spring 927, and the left-hand winding of relay 923 to grounded battery. In position 6 of sequence switch 55 913 and as long as relay 923 remains energized, the magnet 915 is maintained energized by current flowing from grounded battery, through its winding, the lower right-hand contact of sequence switch spring 910, the left-hand front contact and armature of relay 923, the outer right-hand back 60 ture of relay 923, the outer right-hand back 65

contact and armature of relay 903, and the upper contact of sequence switch spring 909 to ground. Thus the wipers 925 are moved until the test wiper 953 reaches the terminal of an idle trunk, i. e., one to which no ground 70 is connected. The above traced circuit through the right-hand winding of relay 923 is then opened, and as soon as the brush 928 engages one of the insulated segments 75 930, and thus opens the circuit through the left-hand winding of relay 923, this relay becomes deenergized and, by opening the circuit of magnet 915, causes the arresting 80 of the incoming selector 917. A circuit is closed from ground, through the upper contact of sequence switch spring 909, the right-hand outer armature and back contact of relay 903, the left-hand armature and back contact of relay 923, the right-hand contacts of sequence switch spring 912; and the power magnet of sequence switch 913 to grounded battery, for driving this sequence switch out of position 6 and into position 7.

A circuit is now closed from ground through the upper contact of sequence switch 90 937, the right-hand back contact and armature of relay 923, the test wiper 953, and the multiples of the seized test terminal 954, thus providing a guard for the seized trunk.

Final brush selection.

When sequence switches 913 and 613 reach positions 7 and 18 respectively, the fundamental circuit is again closed and the relays 100 632 and 903 become energized. Relay 903 closes a locking circuit for itself in the above described manner a circuit from ground, through the upper contact of sequence switch spring 909, its outer armature and 105 front contact, the left-hand contacts of sequence switch spring 924, and the power magnet of sequence switch 913 to grounded battery, for driving this sequence switch out of position 7 and into position 8. A circuit 110 is now closed from grounded battery, through the windings of a relay 5 (Fig. 11), the lower left-hand contact of sequence switch spring 6, trunk conductor 7, wiper 955 of selector 917, the upper right-hand 115 contact of sequence switch spring 910, the right-hand outer front contact and armature of relay 903, and the upper contact of sequence switch spring 909 to ground. Relay 5 closes a circuit from ground, through its 120 left-hand armature and front contact, the upper right-hand and lower left-hand contacts of sequence switch spring 8, and the winding of a relay 3 to grounded battery. Relay 3 locks up through its right-hand 125 armature and front contact, resistance 2, conductor 933, wiper 953, the right-hand armature and back contact of relay 923, and the upper contact of sequence switch spring 937 to ground; and closes a circuit from ground 130

through its left-hand armature and front contact, the upper right-hand contact of sequence switch spring 9, and the power magnet of sequence switch 10 to grounded battery. The sequence switch 10 is moved out of position 1 and under the control of its normal spring 11, into position 2. A circuit is now closed from grounded battery, through the winding of magnet 12, the left-hand contacts of sequence switch spring 13, the right-hand front contact and armature of relay 5, the lower right-hand contact of sequence switch spring 6, conductor 7, wiper 955 of selector 917, the upper right-hand contact of sequence switch spring 910, the right-hand outer front contact and armature of relay 903, and the upper contact of sequence switch 909 to ground. Magnet 12 becomes energized, and by attracting its armature, presses a brush rod 39 of connector 1 against a roller 20 constantly rotating in the direction indicated by the arrow. The wipers and the brushes of the connector will thus be moved in an upward direction.

When brush 14 engages a conducting segment 15, a circuit is closed from ground, through brush 14, conducting segment 15, the upper right-hand contact of sequence switch spring 16, the lower left-hand contact of sequence switch spring 17, trunk conductor 18, wipers 956 of selector 917, the upper right-hand contact of sequence switch spring 905, and the lower right-hand contact of the sequence switch spring 904 to the winding of relay 903, causing thus the shunting out of the sender stepping relay 632. When the brush 14 successively engages the insulated segments 19, this shunt is opened and the relay 632 is permitted to become energized. The relay 632 causes thus, through the agency of magnet 634, the stepping of the sender wipers.

Upon the fourth deenergization of magnet 634 and as soon as wiper 635 reaches terminal No. 3 in section C, circuit is closed from grounded battery, through the winding of relay 633, conductor 637, the left-hand contact of sequence switch springs 638, conductor 639, the lower right-hand contact of sequence switch spring 661, conductor 837, the outer armature and back contact of relay 812, the outer armature and front contact of relay 814, terminal No. 3 of the sender, wipers 635, 636, conductors 642, the lower left-hand armature of sequence switch spring 643, conductor 644, the left-hand contact of sequence switch spring 645, the back contact and armature of magnet 634, and sequence switch contact 646 to ground. The relay 633 becomes energized, opens the fundamental circuit and moves the sequence switch 613 out of position 18 into position 1, whereupon the magnet 634 is operated to restore the sender to normal and open the circuit of relay 633 in the same manner as

above described. Upon the restoration of the sender, the magnet 634 becomes deenergized.

A circuit is now closed from ground through sequence switch contact 611, the right-hand contact of sequence switch spring 612, and the power magnet of sequence switch 600 to grounded battery, to move the sequence switch 600 out of position 15 and into position 16. As soon as the sequence switch 600 reaches position 16, a circuit is closed from ground through sequence switch contact 611, the left-hand contact of sequence switch spring 612, and the power magnet of sequence switch 613, to grounded battery, for driving this sequence switch out of position 1 and into position 2. Upon the opening of the fundamental circuit, relay 903 becomes deenergized and opens the circuits of the magnet 12 and the relay 5. Upon the deenergization of magnet 12, the connector is arrested in its upward movement, and relay 5 closes a circuit from ground, through its left-hand armature and back contact, the upper left-hand and lower right-hand contacts of sequence switch spring 8, and the power magnet of sequence switch 10 to grounded battery, for moving this sequence switch out of position 2 and into position 3. The relay 903 also closes the above traced circuit for moving sequence switch 913 out of position 8 and into position 9.

Final tens selection.

When sequence switches 913 and 613 reach positions 9 and 2 respectively, the fundamental circuit is again closed and relays 903 and 632 become energized. Relay 903 causes the movement of the sequence switch 913 out of position 9 and into position 10, and again closes the circuit of relay 5. Relay 5 closes a circuit including its left-hand armature and front contact, and the right-hand contacts of sequence switch spring 8, for moving sequence switch 10 out of position 3 and into position 4, whereupon magnet 12 is again energized in the above described manner and causes the upward movement of the connector. In view of the fact that in position 3 of the sequence switch 10 the tripping magnet 20 was energized by a circuit including the contact of sequence switch spring 21, as soon as the connector starts in its upward movement, the fourth set of brushes 22 of the connector will be tripped. Whenever brush 23 engages conducting segment 24, a circuit is closed from ground through brush 23, conducting segment 24, the lower right-hand contact of sequence switch spring 16, the lower left-hand contact of sequence switch spring 17, to the winding of relay 903, for causing the shunting of the stepping relay 632 of the sender, whereupon magnet 634 is operated in the

above described manner. Whenever brush 23 engages an insulated segment 25, this shunt is removed, and thus the sender stepping relay is energized.

- 5 The called subscriber's number being 9876, eight tens impulses must be received by the sender before the fundamental circuit is opened by relay 633. As above described, in response to the actuation of the No. 7 10 tens key, the final tens register is set to arrest the sender with its wiper 635 on the No. 2 terminal in section C. Should the sender be arrested in this position, the connector wipers 22 would be moved only by 15 three steps and would thus seize one of the subscribers' lines 9820 to 9829 (See Fig. 13). The circuit of relay 633 may be traced from grounded battery, through the winding of this relay, conductor 637, through right-hand contact of sequence switch spring 638, the lower left-hand contact of sequence switch spring 662, conductor 838, the outer armature and back contact of relay 816, the outer armature and back contact of relay 20 25 819, terminal No. 2 of the sender, wipers 635 and 636, conductor 642, conductor 835, armature and back contact of relay 832, conductor 841, the left-hand contact of sequence switch spring 663, the right-hand contact of 30 sequence switch spring 645, the back contact and armature of magnet 634 and sequence switch contact 646 to ground. In view of the fact, however, that in response to the closure of contact 417 of the No. 7 tens key, 35 the relay 832 was energized, this circuit cannot be established and, therefore, the sender is permitted to continue its operations until the terminal No. 2 in section D is reached. A circuit is then closed from grounded battery, through the winding of relay 633, conductor 637, the right-hand contact of sequence switch 638, the lower left-hand contact of sequence switch spring 662, conductor 838, the outer armature and back 40 45 contact of relay 816, the outer armature and back contact of relay 819, the terminal No. 2 in section D, wipers 635 and 636, conductor 657, the back contact and armature of magnet 634, sequence switch contact 646 to 50 ground. Relay 633 becomes energized, opens the fundamental circuit and causes the movement of sequence switch 613 out of position 2 and into position 3, whereupon magnet 634 is operated to restore the sender 55 and cause the deenergization of relay 633. When the sender reaches its normal position, the sequence switch 613 is moved out of position 3 and into position 4.
- Upon the opening of the fundamental circuit, relay 903 becomes deenergized and causes the movement of sequence switch 913 out of position 10 and into position 11 in the same manner as above described. The circuit of relay 5 is opened and this relay moves 60 65 the sequence switch 10 out of position 4 and

into position 5. The circuit of magnet 12 is now opened and thus the connector arrested in its upward travel.

Final units selection.

70

When the sequence switches 913 and 613 reach positions 11 and 4 respectively, the fundamental circuit is again closed through the upper contacts of sequence switch spring 631 and the left-hand contact of sequence switch spring 630, whereupon relays 632 and 903 become energized. The relay 903 causes the movement of the sequence switch 913 out of position 11 and into position 12, and closes the circuit of relay 5. Relay 5 closes 80 the above traced circuit through the right-hand contacts of sequence switch 8 and causes thus the movement of sequence switch 10 out of position 5 and into position 6. A circuit is now closed from grounded battery, through the winding of magnet 26, the lower right-hand contact of sequence switch spring 13 and then through the above traced circuit for magnet 12 to ground at sequence switch spring 909. Magnet 26 presses the 90 brush rod 39 against a roller 27 constantly rotating in the direction indicated by the arrow, but now, due to the fact that the roller 27 is slower than roller 20, the connector wipers and brushes move at a slower 95 rate of speed. Whenever the brush 14 engages the conducting segment 15, a circuit is closed from ground through brush 14, conducting segment 15, the upper right-hand contact of sequence switch spring 16, and the left-hand contact of sequence switch spring 17 to the winding of relay 903. Due to the closure of this shunt, the relay 632 becomes deenergized, but becomes energized whenever this shunt is opened, due to the engagement of 100 an insulated segment 28 by brush 14. Under the control of relay 632, magnet 634 is operated to rotate the wipers of the sender. All the final units register relays are energized and, therefore, the sender would be 110 stopped when the wiper 635 reaches the terminal No. 1 in section C, the circuit of relay 633 being traceable in the same manner as above described in connection with the sending of the final tens impulses, with the difference that this circuit now leads through the right-hand contact of sequence switch spring 663, the left-hand armature of relay 821, instead of armature and back contact of relay 830, and then through the armatures and contacts of the final units register relay. Should the sender be arrested in this position and the fundamental circuit opened by relay 633, then, instead of the line No. 9876, the line 9871 would be selected (see 120 Fig. 13). In view of the fact that the relay 821 was energized in response to the depression of the No. 6 units key, the circuit of relay 633 is not closed until the sender 125 wipers take five additional steps, whereupon 130

a circuit is closed from grounded battery, through the winding of relay 633, conductor 637, the right-hand contact of sequence switch 638, the left-hand upper contact of sequence switch spring 662, conductor 840, the outer armature and front contact of relay 823, the middle armatures and front contacts of relays 826 and 822, the terminal No. 1 in section D, wipers 635 and 636, conductor 657, the back contact and armature of magnet 634 and sequence switch contact 646 to ground. Relay 633 becomes energized and opens the fundamental circuit and moves the sequence switch 613 out of position 4 and into position 5, whereupon magnet 634 is operated to restore the sender to normal. Upon the restoration of the sender, sequence switch 613 is moved into position 6 in the above described manner.

20 Upon the opening of the fundamental circuit, relay 903 becomes deenergized, moves the sequence switch 913 out of position 12 and into position 13, and causes the deenergization of relay 5 and magnet 26. Upon 25 the deenergization of relay 5, the sequence switch 10 is moved into position 7.

In view of the fact that in a semi-mechanical connection the sending out of stations impulses is not necessary, means are 30 provided for preventing the sending out of impulses under the control of the stations register in position 6 of sequence switch 613. This means consists of contacts of the class register controlling sequence switch 35 706. As soon as the sequence switch 613 reaches position 5₄, a circuit is closed from grounded battery through the winding of relay 633, conductor 637, the right-hand contact of sequence switch spring 638, the upper right-hand contact of sequence switch spring 662, and the contact 744 of the class register sequence switch 706 to ground. Relay 633 is energized and by attracting its right-hand armature prevents the closure of 40 the fundamental circuit, and by attracting its left-hand armature, moves the sequence switch 613 out of position 6 into position 7, whereupon relay 633 becomes deenergized. A circuit is now closed from ground, 45 sequence switch contact 666, the lower contact of sequence switch spring 624, conductor 561, terminal 559, wiper 544, the left-hand contacts of sequence switch spring 560, conductor 225, the lower contact of sequence 50 switch spring 224, conductor 257, the lower right-hand contact of sequence switch spring 107 and the power magnet of sequence switch 108 to grounded battery. Due to the closure of this circuit the sequence switch 55 60 108 is moved out of position 11 and into position 16, whereupon a circuit is closed from ground through the secondary winding of repeating coil 104, the left-hand contact of sequence switch spring 142, wiper 65 141, terminal 140, conductor 143, sequence

switch contact 174, wiper 173, conductor 900, the lower left-hand contact of sequence switch spring 905, the lower left-hand contact of sequence switch spring 904, and the winding of relay 903 to grounded battery. 70 Relay 903 becomes energized and closes the above traced circuit for driving the sequence switch 913 out of position 13 and into position 15, whereupon the relay 903 becomes deenergized. While the sequence 75 switch 913 is moving through position 14 a circuit is closed through the upper contacts of sequence switch spring 927 and the left-hand winding of relay 923 to grounded battery, for energizing this relay. If, as 80 in the present case, the selector wipers 925 are set to seize a connector through which access may be had to subscribers' lines, Nos. 9800 to 9899, then the brush 944 is making contact with a conducting segment 941 85 after the setting of the incoming selector. Therefore, when the sequence switch reaches position 14 and until it moves out of position 15₁, a circuit is closed from ground through the lower contact of sequence 90 switch spring 921, brush 944, conducting segment 941, the right-hand contact of sequence switch spring 931, and the right-hand winding of relay 923 to grounded battery, and thus relay 923 remains energized 95 after the sequence switch 913 moves out of position 14. While the relay 923 is energized, the test terminal 954 and multiples thereof are made busy by virtue of the ground connection through wiper 953 and the right-hand contacts of sequence switch spring 921. Relay 923 being energized when the sequence switch 913 reaches position 15, this sequence switch is immediately driven into position 16, by a circuit extending 100 from grounded battery, through its power magnet, the lower left-hand contact of sequence switch spring 946, the right-hand front contact and armature of relay 923, and the right-hand contacts of sequence 105 switch spring 921 to ground.

In position 14 of the sequence switch 913, the ground at repeating coil 104 is connected through the conductor 900, the lower contacts of sequence switch spring 905, the upper contact of relay 938, wiper 955, conductor 7, the lower left-hand contact of sequence switch spring 6 and the windings of relay 5 to grounded battery. Relay 5 becomes energized and moves the sequence 115 switch out of position 7 and into position 8.

A test circuit is now closed from ground, through the high resistance right-hand winding of test relay 29, the lower contacts of sequence switch spring 30, the low resistance left-hand winding of test relay 29, the right-hand contact of sequence switch spring 31, test wiper 35 of connector 1, and the test terminal of the called line. If this line is idle, then full battery potential ex- 125 130

ists on its test terminal, grounded battery being connected through the winding of the cut-off relay individual to the line to test terminal. Relay 29 becomes energized, and 5 shunts out its high resistance right-hand winding, the shunt path leading through the left-hand armature and back contact of a relay 32 and the left-hand armature and front contact of relay 29. The potential 10 on the multiples of the test terminal is now reduced, and the seizure of this line by another final selector is prevented. Relay 29 closes also a circuit from ground, through the right-hand armature and back contact 15 of relay 32, its right-hand armature and front contact the lower left-hand contact of sequence switch spring 9, and the power magnet of sequence switch 10 to grounded battery, for driving this sequence switch out 20 of position 8 and into position 14. The sequence switch will be moved into position 14, from which position it is driven into position 16 under the control of relays 32 and 29, and the lower left-hand contact of 25 sequence switch spring 9.

The sequence switch 913 was moved into position 16 for the reason that the called subscriber's station 33 may be signaled by current generated from source 945. The subscribers' stations, the bell of which responds 30 to signaling current generated by source 943, are grouped separately from such stations as 33, and when the incoming selector is set onto a connector through which access may be 35 had to such stations, the brush 944 does not engage the conducting segment 941, and therefore relay 923 is not maintained energized but falls off and thus does not cause sequence switch 913 to move immediately out 40 of position 15.

In position 16 of the sequence switch, the signaling current source 943 is affected. In position 15 of sequence switch 913, a circuit is closed from grounded battery, through the 45 lower contact of sequence switch spring 909, the outer armature and back contact of relay 903, the left-hand armature and back contact of relay 923, the lower right-hand and upper left-hand contacts of sequence switch spring 50 912, the armature and back contact of relay 950, the back contact and armature of relay 941, the winding of relay 938, the back contact and armature of relay 948, sequence switch contact 949, conductor 900, wiper 173, 55 sequence switch contact 174, conductor 143, terminal 140, wiper 141, the left-hand contact of sequence switch spring 142, the secondary winding of repeating coil 104 to ground. Relay 938 becomes energized. Relay 941 cannot become energized in parallel 60 with relay 938, because this relay is short-circuited through the back contacts of relays 950 and 941. Relay 938 closes the ringing circuit, which extends from ground through 65 its upper armature and front contact, wiper

955, conductor 7, the upper contact of sequence switch spring 6, wiper 84, the bell at the called substation 33, wiper 36, the lower contacts of sequence switch spring 17, conductor 18, wiper 953, the lower armature and 70 front contact of relay 938, the right-hand contact of sequence switch spring 951, and the right-hand winding of relay 950 to the current source 945.

The called subscriber is thus signaled until 75 he removes the receiver from the switchhook, whereupon relay 950, which is marginal in operation, becomes energized, opens the shunt around the winding of relay 941, which relay locks up through its armature 80 and front contact, and shunts out relay 938, which becomes deenergized. The supervisory relays SR¹ and SR² become now energized. Upon the energization of SR², a circuit is closed from ground, through the 85 armature and front contact of this relay, the winding of relay 948, the upper left-hand and lower right-hand contacts of sequence switch springs 912, the back contacts and armatures of relays 923 and 903 and the 90 lower contact of sequence switch spring 909 to grounded battery, whereupon relay 948 becomes energized and replaces the ground which was connected through the repeating coil by a ground connected through its front 95 contact to the winding of relay 941.

Restoration of cord finder and sender selector.

When the sequence switch 108 moves out 100 of position 11 and opens the upper right-hand contact of sequence switch spring 112, the relay 545 becomes deenergized and closes a circuit from ground through its right-hand armature and back contact, the lower left-hand contact of sequence switch spring 567, 105 and the power magnet of sequence switch 516 to grounded battery, for moving this sequence switch out of position 15 and into position 16. A circuit is now closed from 110 ground through contacts of sequence switch spring 526, and the winding of magnet 568 to grounded battery, and another circuit from ground through the right-hand contact of sequence switch spring 562 and the 115 winding of magnet 569 to grounded battery. These magnets become energized and press brush rods 530 and 552 against rollers 570 and 571 respectively, constantly rotating in the direction indicated by the arrow. Under the control of the rollers 570 and 571, the cord finder and the sender selector are restored to normal. As soon as the brush 555 of the sender selector reaches its normal position, a circuit is closed from ground 120 through the lower left-hand contact of sequence switch spring 527, brush 555, conducting segment 572, the upper right-hand contact of sequence switch spring 567, and the power magnet of sequence switch 516 to 125 130

grounded battery, for moving this sequence switch out of position 16 into position 17. The circuit of magnet 569 is now opened. As soon as the cord finder reaches its normal position, a circuit is closed from ground through brush 536, conducting segment 573, the upper left-hand contact of sequence switch 567, and the power magnet of sequence switch 516 to grounded battery, 5 whereupon the sequence switch is moved out of position 17 and into position 18, and opens the circuit of magnet 568. As soon as the allotter 583 is moved into position 1 under the control of a sequence switch like 516, 10 a circuit is closed from ground through allotter contact 586, the lower right-hand contact of sequence switch 567, and the power magnet of sequence switch 516 to grounded battery, for driving this sequence switch 15 out of position 18 and into position 1. In this position the cord finder and sender selector are under the control of the sequence switch 516 which may be again employed in extending an operator's keyboard to an 20 idle sender. 25

Restoration of the sender and the registers.

When the wiper 520 of the sender selector leaves terminal 551, the locking circuit of relay 608 is broken, and this relay becomes de- 30 energized and closes a circuit through its lower armature and back contact, the lower contact of sequence switch 609 and the power magnet of sequence switch 600 to grounded 35 battery, for driving this sequence switch out of position 16 and into position 18. A circuit is now closed from ground through sequence switch spring 667, upper right-hand contact of sequence switch spring 647 and 40 the power magnet of sequence switch 613 to grounded battery, and this sequence switch 613 is driven out of position 7 and into position 1. As soon as it reaches position 1 a circuit is closed from ground through sequence switch spring 611, the right-hand contact of sequence switch spring 612, and the power magnet of sequence switch 600 to grounded battery, and the sequence switch 600 is driven out of position 18 into 45 position 1. 50

When the sequence switch 600 left position 15, the relays of the district group, office group, office brush, and class registers became deenergized, and when the sequence 55 switch left position 16, the relays of the other registers became deenergized.

In the above description, the fundamental circuit for controlling the various selector switches was traced as leading through the 60 lower contacts of sequence switch springs 228 and 226, and the circuit for driving sequence switch 108 out of position 11 was traced as leading through the lower contact of sequence switch spring 224. This will be 65 the case if these circuits are closed when the

sequence switch 202 is in the listening-out position 11. Should, however, the closure of any one of these circuits be required while the sequence switch 202 is still in the listening-in position 7, these circuits will be completed through the upper contacts of the mentioned sequence switch springs and the lower contacts of sequence switch springs 269, 266 and 256. 70

Restoration of the selector switches. 75

If disconnection is desired, the calling and called subscribers restore their receivers to the switchhook. This results in the deenergization of the supervisory relays SR, SR' and SR². Upon the deenergization of relay SR², the ground is removed from the winding of relay 948, and this relay, by deenergizing, restores the control of relay 941 to the district selector. Upon the deenergizations of relays SR and SR', a well-known clearing-out signal is displayed at the operator's position, whereupon the operator removes plug 101 from jack 102. The cut-off relay of the calling line becomes deenergized and relay 103 becomes deenergized and closes a circuit from ground through its armature and back contact, conductor 270, the upper contact of sequence switch spring 271, and the power magnet of sequence switch 202 to grounded battery, whereupon this sequence switch is moved out of position 11 and into position 1. A circuit is closed thereupon from ground through the back contact and armature of relay 103, conductor 270, the lower contact of sequence switch spring 271, conductor 272, upper left-hand contact of sequence switch spring 107 and the power magnet of sequence switch 108 to grounded battery, for moving this sequence switch out of position 16 into 100 position 18. A circuit is now closed from ground through the upper right-hand contact of sequence switch spring 136 and the winding of a magnet 179 to grounded battery. The magnet 179, by attracting its armature, presses the brush rod 121 against a roller 180 constantly rotating in the direction of the arrow, whereby the district selector is restored to normal. As soon as it reaches its normal position, a circuit is closed 105 from ground through brush 125, the normal conducting segment 181, the lower left-hand contact of sequence switch spring 107 and the power magnet of sequence switch 108 to grounded battery, for driving this sequence switch out of position 18 into position 1. Magnet 179 becomes deenergized. 110

As soon as wiper 138 leaves terminal 139, the locking circuit of relay 149 is opened and this relay closes a circuit from ground through its right-hand armature and back contact, the lower right-hand contact of sequence switch 151, and the power magnet of sequence switch 152 to grounded battery, for driving this sequence switch into position 18. 130

In position 18 of this sequence switch a circuit is closed from grounded battery, through the winding of magnet 182 and the upper right-hand contact of sequence switch 5 spring 168 to ground. Magnet 182 becomes energized and, by attracting its armature, presses the brush rod 156 against the roller 183 constantly rotating in the direction indicated by the arrow, whereby the office selector 10 is restored to normal. When the selector switch reaches its normal position, a circuit is closed from ground through brush 159, a normal conducting segment 184, sequence switch contact 185 and the power 15 magnet of sequence switch 152 to grounded battery, for moving this sequence switch out of position 18 into position 1, whereupon the magnet 182 becomes deenergized.

As soon as the wiper 170 leaves terminal 20 172, the locking circuit of relay 911 is opened and this relay closes a circuit from ground through its right-hand armature and back contact, the lower right-hand contact of sequence switch spring 946, and the power 25 magnet of sequence switch 913 to grounded battery, for driving this sequence switch into position 18. A circuit is now closed from grounded battery, through the winding of magnet 957, the lower right-hand contact 30 of sequence switch spring 937 to ground. Magnet 957, by attracting its armature, presses the brush rod 916 against the roller 958 rotating in the direction indicated by the arrow, whereby the incoming selector 35 is restored to normal. As soon as the selector is restored to its normal position, a circuit is closed from ground through the lower right-hand contact of sequence switch spring 921, brush 934, a normal conducting 40 segment 959, the upper right-hand contact of sequence switch spring 946, to the power magnet of sequence switch 913, to grounded battery, for driving this sequence switch out of position 18 and into position 1, whereupon 45 the circuit of magnet 957 is opened. Upon the restoration of the office selector, the relay 941 becomes deenergized.

As soon as wiper 953 leaves terminal 954, the locking circuit of relay 3 is opened and 50 this relay closes a circuit from ground through its left-hand armature and back contact, the upper left-hand contact of sequence switch spring 9, the power magnet of sequence switch 10, to grounded battery, for driving this sequence switch out of position 16 and into position 18. A circuit is now closed from grounded battery, through the winding of a magnet 41, the lower left-hand contact of sequence switch spring 42, 55 to ground. Magnet 41 by attracting its armature, presses the brush rod 39 against roller 43, constantly rotating in the direction of the arrow, whereby the final selector is restored to normal. As soon as 60 it reaches its normal position, a circuit is

closed from ground through brush 43, a normal conducting segment 44, the lower right-hand contact of sequence switch spring 9, and the power magnet of sequence switch 10 to grounded battery, for moving this sequence switch out of position 18 and into 70 position 1. The circuit of magnet 41 is then opened. As soon as the sequence switch 10 leaves position 16, the relay 29 becomes deenergized.

75

Attempted connection to a busy line.

If the called line is busy, which fact is indicated by the reduced battery potential on its test terminal, then the relay 29, which is marginal in operation, cannot become energized in position 8 of the sequence switch 10. In view of the fact that relays 29 and 32 are deenergized, the sequence switch 10 is left in position 14 and a circuit is closed from grounded battery through the winding of down-drive magnet 41, the upper contact of sequence switch spring 42, the back contact and right-hand armature of relay 29, and the right-hand back contact and armature of relay 32 to ground. Under the control of the magnet 41 the final connector is restored to normal. As soon as it reaches its normal position, a circuit is closed from ground through brush 23, conducting segment 44, the lower right-hand contact of sequence switch spring 9, and the power magnet of sequence switch 10 to grounded battery, for moving this sequence out of position 14 and into position 95 17. A busy tone is now connected to the calling line from a signaling apparatus 48 through the upper contacts of sequence switch spring 30. As soon as the calling subscriber perceiving the busy tone restores the receiver to the switchhook, the supervisory relay SR becomes deenergized, whereupon the operator causes the restoration of the switches in the above described manner.

100

105

Arrangement of the keyboard.

110

The above description of the operation of the system in connection with the establishment of a semi-mechanical call is deemed to be sufficient to enable one skilled in the art to understand the operation of a system embodying the features of the present invention. The setting of the registers and therefore the operation of the sender may be varied in accordance with the keys depressed by the operator. In the following 115 a brief description will be given of the various circuit conditions obtained, due to the depression of the various keys. The contact of a key will be referred to as the first, second, third, etc., contacts of the number X office, 1000's, 100's, etc., keys. Contact 353 and other contacts in one row with this contact will be referred to as the first contact of the No. B office key; contact 354 as the second contact; contact 355 as the 120 125 130

third contact; and contact 356 as the fourth contact of this office key.

Office and tandem keys.

- 5 The closure of the first contacts and the closure of the second contacts of the Nos. 6, 5, 1 and 0 tandem hundreds keys results in the tripping of a certain set of brushes of the district selector. In case of the No. A 10 office key, the closure of the first contact does not result in the energization of relay 349, as was the case with the No. B office key. Due to the fact that relay 349 is not energized when the sequence switch 210 passes 15 through position $1\frac{1}{4}$, and in positions 1 and 2 of the sequence switch 600, the class register relay 702 will not be energized, and for this reason, when the sequence switch 600 reaches position 2, the class register controlling sequence switch 706 is moved out of 20 position 1 and into position 2. The second contact of the No. 0, and Nos. 5 and 6 tandem hundreds keys results in the energization of relay 350, which relay, by connecting the high resistance 327 in series with relay 702, prevents the energization of this relay, but permits the energization of relay 703. Relay 702 causes the sequence switch 706 to move into position 2, and due to the energized condition of relay 703 the sequence switch is prevented from moving out of that 25 position.
- When the first contact of the No. A office key is depressed, relay 703 remains also de- 30 energized and will cause the class register sequence switch 706 to move into position 3. The depression of the second contact of the No. 1 tandem hundreds key produces the same result as the depression of the first 35 contact of the No. B office key, with the exception that instead of the second, the fifth set of brushes of the district selector will be tripped. The second contacts of all the office keys operate in a like manner. The first 40 contacts of the tandem hundreds keys are arranged to produce substantially the same results as the second contact of the office keys. If the Nos. 9, 8, 7 and 6 tandem hundreds keys are used, then neither relay 303 45 nor relay 348 is actuated, and for this reason, in position $1\frac{1}{4}$ of sequence switch 210, and positions 1 and 2 of sequence switch 600, the class register relays 704 and 709 remain deenergized and cause the movement of sequence switch 706 into position 13. Relay 305 remains also deenergized, and for this 50 reason, in position 2 of sequence switches 210 and 600, both windings of relay 220 are connected in series with the marginal relay 700, and therefore this relay causes the movement of sequence switch 706 into position 10. Relays 303 and 348 remain deenergized with the above-mentioned effect. The actuation of the contacts of Nos. 4, 3, 2 55 and 1 tandem hundreds keys results in the

energization of relays 305 and 348. Relay 305 operates in the above-mentioned manner, and relay 348 connects the high resistance 363 (position $1\frac{1}{4}$ of sequence switch 210) in series with the relays 704 and 709, with the result that only relay 709 becomes energized, and relay 704, by remaining deenergized, causes the movement of the sequence switch 706 into position 4.

In response to the actuation of the third contact of the No. A office key, relays 310, 306, and 311 become energized. The energization of relay 310 results in the energization of the district group register relays 717 and 718, and the energization of relay 306 in the energization of the translating relay 742. The actuation of the third contact of the No. C office key results in the energization of the relay 322. When sequence switch 210 reaches position 4, relay 322 connects the low resistance left-hand winding of relay 220 in circuit and causes, therefore, the energization of relay 721.

The actuation of the fourth contact of the No. A office key results in the energization of relays 344, 328, 317 and 313. In position 5 of sequence switch 210, the conductor 240 is connected through the front contact of relay 328 to the low resistance winding of relay 233, and for this reason the marginal office brush register relay 722 is energized. In position $4\frac{1}{4}$ of sequence switch 210, the conductor 239 is connected through the front contact of relay 317 to the high resistance 327, and for this reason relay 725 becomes energized, but the marginal relay 724 remains deenergized.

The closure of the fourth contact of the No. C office key results in the energization of relays 329, 349 and 344. Relay 347 connects the conductor 239 to the low resistance 329, with the result that in position $4\frac{1}{4}$ of sequence switches 210 and 600, both relays 725 and 724 become energized.

The actuation of none of the contacts of the tandem keys can cause the energization of relay 344, but in view of the fact that in response to the depression of any key in the tandem hundreds, tandem tens, and tandem units rows, the respective row contacts 364, 365 and 366 of these keys are closed, the relay 344 is energized by current flowing through a circuit established through these contacts in series, whereupon the relay closes the circuit for driving the sequence switch 210 out of position 1 and into position 2.

The tandem tens keys operate to set the district group register, and thus operate substantially in the same manner as the third contacts of the office keys. The depression of the No. 9 key results in the energization of relays 351 and 311; the depression of the No. 7 key, the energization of only relay 311; the No. 6 key, relays 310 and 311; the No. 5 key also relays 310 and 311. Gener- 130

ally stated, the actuation of the various keys will actuate a combination of relays 311, 310, and 351 to determine the setting of the district group register, by connecting conductors 267 and 321 through high or low resistances in series with the marginal relays of the district group register. Only the first five keys of the tandem keys group, that is to say the keys 0 to 4, cause the actuation of relay 306, and for this reason only the depression of those keys will cause the energization of the translating relay 742.

The tandem units keys 5 to 9 operate relays 330, 329 and 352 in a certain combination, for determining the setting of the office group register. It will be noted that of these keys only the first five (0 to 4) cause the operation of relay 322, which relay when energized causes the operation of the office translating relay 721.

Thousand keys.

The first contacts of the thousands keys are wired in such a manner as to produce the sending of the same number of impulses, irrespective of which of two neighboring keys, such as 9, 8 and 7, 6, etc., are depressed. The reason for this is that, as above stated in connection with the translation system used, any one of two thousand lines may be reached through one section of terminals of the incoming selector. The first contacts of the thousands keys may connect both windings, or only the low resistance winding of relay 233, in series with the relays of the incoming brush register, causing, thus, the selective operation of this register. The second contacts of the Nos. 3, 2, 1 and 0 thousands keys connect the low resistance 339 instead of the high resistance 327, as is the case with the second contacts of the Nos. 9 and 8 thousands keys in circuit, for operating the incoming group registers. The even number thousands keys carry also a third contact, the closure of which results in the connection of the low resistance 339 in series with sensitive relay 807. Thus, if an even number thousands key is depressed, then the incoming group register will be set to stop the sender in position 0 or 1, depending on the operation of relay 809, whereas if the odd number thousands keys are depressed, the sensitive relay 807 remains deenergized and causes, depending on the energized or deenergized condition of relay 809, the stopping of the sender in positions 2 or 3. The reason for this is that the first two groups of each section of the terminal bank of the incoming selectors contain terminals having an even, and the second two sections an odd thousands number. Therefore, if an even number thousands key is depressed, the incoming brushes should not be stepped by more than one or two steps, whereas if an odd number thousands key is

depressed, such brushes must be stepped by three or four steps.

Hundred keys.

The first contacts of the Nos. 4 and 9 hundreds keys will connect the high resistance 327 in series with the final brush register relays 812 and 811, and thus, by causing the operation of relay 812 and preventing the energization of relay 814, cause the stepping of the sender onto terminal No. 2 or 3. Relay 811 being deenergized, the sender wiper 635 is stopped on terminal No. 4. Five impulses will thus be sent for the purpose of controlling the final brush selection if the hundreds number is 9 or 4, that is to say, if the subscriber's line is terminating in the last section of the terminal bank of the final selector, the first contacts of keys 6, 5, 1 and 0 will cause the connection of the low resistance 339 in circuit with the final brush register relays, and cause the energization of both relays 811 and 812. Depending on the energized or deenergized condition of relay 814, the sender will be stopped in position 0 or 1, and thus one or two final brush selecting impulses will be sent out. The reason for this is that subscribers' lines, the hundreds digit of which is 6, 5, 1, or 0, terminate in the first or second sections of the terminal bank of final selectors.

The second contacts of the hundreds keys control the operation of the marginal final brush register relay 814. The second contacts of keys 9 to 5 connect both windings of the relay 220, and the second contacts of keys 4 to 0, the low resistance winding of this relay in circuit with the marginal relay 814. Thus, if the hundreds digit of the desired subscriber's number is 9 to 5, then relay 814 remains deenergized, and may cause, depending on the energized or deenergized condition of relay 812, the sending of three final brush selecting impulses. Thus, if any one of the No. 9 to 5 hundreds keys is depressed, due to the closure of their second contact, the relay 809 of the incoming group register remains deenergized, and will thus cause the sending of two or four incoming group impulses, depending on the energized or deenergized condition of relay 807. The reason for this is that the trunks leading to the final selectors through which access may be had to subscribers' lines, the hundreds digit of which is 5 to 9, terminate in the second and fourth groups of the various sections of the terminal banks of the incoming selectors. The actuation of the second contacts of the No. 4 to 0 hundreds keys results in the energization of relay 809, and, therefore, this relay will predetermine the sending of one or three impulses, because, if the subscriber's line number is 0 to 400, then the incoming brushes must be stepped to the first or third groups.

The third contacts of the hundreds keys control the operation of the final brush register relay 814. If an even number hundreds key is depressed, then the third contact of such key connects both windings of relay 233 in series with relay 814, and if the odd number hundreds key is depressed only, the low resistance right-hand winding of relay 233 is connected in series with such marginal relay. Therefore, depending on the energized or deenergized condition of relay 812, the relay 814 causes, in case an even number hundreds key is depressed, the sending of three final brush selecting impulses, and in case an odd number key is depressed, the sending of four final brush selecting impulses. The reason for this is that the hundreds digit of the subscribers' lines terminating in the third section of the final selector is odd, and the hundreds digit of the lines terminating in the fourth section of the final selector is even.

Tens keys.

25 The first contacts of the odd number tens keys connect low resistance left-hand windings of relay 220 in series with relay 819 of the final tens register and the first contacts of the even number tens keys, both windings 30 of relay 220, and if the tens digit of the desired subscriber's line is even, the relay 819 remains deenergized; and, if the tens digit is odd, then the relay becomes energized. In the former case three or five, and in the latter case four or two final tens impulses are sent. The reason for this is that in the third and fifth groups of a section of the terminal bank of the final selector, subscribers' lines Nos. XX20, to XX29, and XX40 to XX49 40 respectively terminate, and in the second and fourth groups of such terminal bank sections subscribers' lines XX10 to XX19, and XX30 to XX39 respectively terminate.

The actuation of the second contacts of 45 the Nos. 9 to 4 tens keys results in the connection of the high resistance 363 in series with the relays 816 and 815. In response to the energization of relay 816, relay 815 remaining deenergized, five final tens impulses 50 will be sent, because in the fifth group of a final selector terminal bank section, subscribers' lines Nos. XX40, to XX49, and in the tenth group of such sections subscribers' lines Nos. XX90 to XX99 terminate.

55 The second contacts of the tens keys 6, 5, 1 and 0 will cause the connection of the low resistance 319 in series with the relays 816 and 815, whereby both these relays become energized. Depending on the energized or deenergized condition of relay 819, one or two final tens impulses will be sent, because the subscribers' lines Nos. XX00 to XX09, and XX10 to XX19 terminate in first and second groups of the various final selector 60 terminal bank sections respectively.

The closure of the third contacts of the Nos. 9 to 5 tens keys results in the energization of relay 832, whereby five impulses, in addition to those predetermined by the setting of the register, are sent, for a purpose 70 which will obviously appear from the above description of the system.

Units keys.

The first contacts of the Nos. 9 and 4 units 75 keys cause the connection of the high resistance 363 in series with the final units register relays 823 and 822, whereby relay 823 will be energized, and relay 822 remains deenergized and thus five units impulses will 80 be sent, the reason being that, in each group of any section of the final selector terminal bank, the units digit 4 or 9 is reached upon the fifth or tenth step of the brushes.

The first contacts of the Nos. 6, 5, 1 and 0 85 units keys connect a low resistance 319 in series with the mentioned final units register relays, whereby one or two final units impulses will be sent, the lines having a unit digit 0, 1, 5 and 6 being accessible in response 90 to the sending of one, two, six or seven final units impulses.

The second contacts of the units keys 9 to 5 connect the low resistance winding of relay 233 in series with relay 821, and this relay 95 upon energization will cause the sending of five additional steps of final units impulses for the above-stated reason. The second contacts of the Nos. 4 to 0 units keys connect both windings of relay 233 in series 100 with relay 820, and therefore this relay does not become energized, and the number of impulses determined by the final units register will not be changed.

The third contacts of the odd number 105 units keys connect both windings of relay 220 in series with the final units register relay 826, and the third contacts of the even number units keys only the low resistance left-hand winding of relay 220. Therefore, 110 if an even number final units key is depressed, relay 826 becomes energized and causes the sending of four or two impulses, whereas, if an odd number final units key is depressed, then this relay causes the sending 115 of three or five impulses.

The operation of the stations register relays will be obvious from an examination of the drawings.

What is claimed is:

1. In a telephone system, a plurality of lines terminating at a central exchange, means including selectively operable switching devices for interconnecting two of said lines, a plurality of variably adjustable senders, each arranged to control the operation of said switching devices, a plurality of controllers at the central exchange, each arranged to control the adjustment of any one of said senders, and means for associating 120

any one of said controllers with any one of said senders.

2. In a telephone system, a plurality of lines, means including selectively operable switching devices for interconnecting two of said lines, a plurality of variably adjustable senders, each arranged to control the operation of said switching devices, a plurality of operators' keyboards, means for associating any one of said keyboards with any one of said senders, and means controlled by the setting of a keyboard for adjusting the associated sender.

3. In combination, a plurality of variably operable senders, a plurality of variably adjustable sender-controlling devices, means for rendering any one of said senders busy, switching means for associating any one of said controlling devices with an idle sender, and means under the joint control of a controlling device and a sender for operating said switching means.

4. In a telephone system, a central office, a plurality of lines terminating thereat, means at said central office including selectively operable switching devices for interconnecting two of said lines, a variably adjustable sender for controlling the operation of said switching devices, a controller at said central office, switching means for associating said controller with said sender, testing means for said switching means, and means responsive to the setting of said controller for determining the adjustment of the associated sender.

5. In combination, a variably operable sender, a variably adjustable controlling device for said sender normally disassociated therefrom, a cord finder switch and a sender selector switch, and means for operating said switches to interconnect said sender and said controlling device.

6. In combination, a variably operable sender, a variably adjustable controlling device for said sender normally disassociated therefrom, a plurality of groups of link conductors, switching means for interconnecting said sender and controlling device by any one of said groups of link conductors, and means under the joint control of said sender and controlling device for operating said switching means.

7. In combination, a variably operable sender, a variably adjustable controlling device for said sender normally disassociated therefrom, a plurality of finder switches, means for connecting said sender to any one of said finder switches, means for selecting one of said finder switches for service, and means for operating said selected finder switch to seize said controlling device.

8. In combination, a variably operable sender, a variably adjustable controlling device for said sender normally disassociated therefrom, a plurality of hunting switches,

a plurality of cord finders, means for selecting a cord finder and a hunting switch for service, and means for operating the selected finder and hunting switch to interconnect said sender and controlling device. 70

9. In combination, a selectively operable switching device, a variably operable sender for controlling the operation of said device, a variably adjustable controller for said sender, a controlling circuit for said sender, 75 switching device and controller, and means for simultaneously associating the controlling circuits of said controller and switching device with the controlling circuit of said sender. 80

10. In combination, a selectively operable switching device, a variably operable sender for controlling the operation of said device, a variably adjustable controller, a controlling circuit for said sender, a switch having 85 a set of movable and a set of stationary contacts, means for extending said controlling circuit to said movable contacts, a controlling circuit for said controller terminating in said set of stationary contacts, 90 and means for operating said set of movable contacts to engage said set of stationary contacts.

11. In combination, a variably operable sender, a variably adjustable controlling device arranged to determine the operation of said sender, a controlling circuit for said sender, and means operative upon the actuation of said controlling device for associating it with said controlling circuit. 95 100

12. In a telephone system, a central office, a plurality of lines terminating thereat, means including selectively operable switching devices for interconnecting two of said lines, a variably operable sender for controlling the setting of any one of said switching devices, a plurality of variably adjustable controlling devices at said central office, means for seizing for use any one of said controlling devices, switching means operative thereupon for associating the seized controlling device with said sender, and means for operating said sender in accordance with the adjustment of the associated controlling device. 105 110 115

13. In combination, a variably operable sender, a plurality of selectively operable switching devices, means for setting any one of said devices in accordance with the operation of said sender, a sender-controlling device normally disassociated from said sender, means for assigning any one of said selectively operable switching devices for control by said sender, and means responsive to the assignment of a switching device 120 125 for associating said controlling device with said sender.

14. In combination, a variably operable sender, a plurality of selectively operable switching devices, means for setting any one 130

of said devices in accordance with the operation of said sender, a sender controlling device normally disassociated from said sender, means for assigning any one of said selectively operable switching devices for control by said sender, a finder switch having a set of movable contacts, a plurality of sets of stationary contacts for said finder switch, one set being provided in common to a controlling device and a switching device, means operative in response to the assignment of a switching device for applying a selectable battery potential to the set of stationary contacts individual to the assigned switching device, a controlling circuit for said sender, means for extending said circuit to said set of movable contacts, motor means for said movable contacts, and a test relay for controlling the operation of said motor means.

15. In combination, a plurality of selectively operable switching devices, a sender arranged to control the operation of any one of said switching devices, a plurality of sender controlling devices, one provided for each of said switching devices, a finder having a set of movable contacts, a plurality of sets of stationary contacts for said finder, one set of stationary contacts being provided for each switching device and its associated sender controlling device, motor means for said movable contacts, a control circuit for said sender, means for extending said circuit to said movable contacts, means for assigning any one of said selector switches for operation, means responsive to the assignment of any one of said switching devices for applying a selectable battery potential to the set of stationary contacts individual to assigned switching devices, and a test relay for controlling the operation of said motor means.

16. In combination, a plurality of groups of selectively operable switching devices, a sender arranged to control the operation of any one of said switching devices, a plurality of sender controlling means, one provided in association with each group of switching devices, a finder switch having movable contacts and a plurality of sets of stationary contacts arranged in sections corresponding to said groups of switching devices, one set of stationary contacts being individual to one group of switching devices and its associated sender-controlling device, means for assigning any one of said switching devices for operation, a control circuit for said sender, means for extending said circuit to said set of movable contacts, motor means for said movable contacts to cause them to engage any one of said stationary contacts, means for applying a selectable battery potential to the set of terminals individual to the group comprising the assigned switching device, and a test relay for

controlling the operation of said motor means.

17. In combination, a plurality of groups of selectively operable switching devices, a sender arranged to control the operation of any one of said switching devices, a sender-controlling device associated with each group of switching devices, a finder switch having a plurality of sets of stationary contacts arranged in sections corresponding to the groups of switching devices, a set of movable contacts for each section of stationary contacts arranged when actuated to engage the sets of stationary contacts of the respective section, a controlling circuit for said sender, means for extending said controlling circuit to any one of said sets of movable contacts, means for assigning any one of said switching devices for operation, means responsive to the assignment of a switching device for applying a selectable battery potential to the set of stationary contacts individual to the group to which the assigned switching device belongs, means also operative upon the assignment of a switching device for actuating the set of movable contacts arranged to engage the stationary contacts of the proper section, motor means for said movable contacts, and a test relay for controlling said motor means.

18. In a telephone system, a calling and a called line, a plurality of variably operable senders, a plurality of selectively operable switching devices, a variably adjustable sender-controlling device for each of said switching devices, means for extending any one of said switching devices to the calling line, means responsive thereto for operatively associating the sender-controlling device of the extended switching device with any one of said senders, means depending on the adjustment of the sender-controlling device for controlling the operation of the associated sender, means for interconnecting the extended switching device and the last mentioned sender, and means depending on the adjustment of said sender for setting said extended switching device to seize the called line.

19. In a telephone exchange system, a calling and a called line, a trunk, a selectively operable switching device, means for extending said trunk to the calling line, means for extending said trunk to said selectively operable switching device, an operator's telephone set, means for connecting it to said trunk, a variably operable sender for controlling the setting of said selectively operable switching device, a sender-controlling device normally disassociated from said sender, and means operative upon the connection of said operator's telephone set to said trunk for associating said controlling device with said sender.

20. In a telephone exchange system, a calling and a called line, a plurality of trunk lines, a variably operable sender, an operator's position comprising a telephone set and a sender-controlling device normally disassociated from said sender, a plurality of listening key switches at said operator's position, one provided for each of said trunk lines, means operative upon the actuation 5 of any one of said listening-key switches for associating said controlling device with said sender, and means for associating said sender with the trunk the associated listening-key switch of which was operated.
- 15 21. In combination, a selectively operable switching device, a variably operable sender for controlling the operation of said device, a registering device associated with said sender, a variably adjustable controller for 20 said registering device, a controlling circuit for said registering device, switching device and controller, means for interconnecting the controlling circuits of said switching device and sender, and means for interconnecting the controlling circuits of said registering device and controller.
22. In combination, a selectively operable switching device, a variably operable sender for controlling the operation of said device, a registering device associated with said sender and arranged to control its operation, a variably adjustable controller for said 30 registering device, switching means for associating said sender with said switching device, another switching means for associating said registering device with said controller, and means for simultaneously operating said two switching means.
- 35 23. In combination, a selectively operable switching device, a variably operable sender for controlling the operation of said device, a registering device associated with said sender and arranged to control its operation, a variably adjustable controller, a controlling 40 circuit for said sender, registering device, controller and switching device, a switch having a set of movable contacts and a set of stationary contacts, means for extending said movable contacts to the controlling circuits of said registering device and sender, means for extending the controlling circuits of said controller and switching device to said stationary contacts, and means for operating said set of movable 45 contacts to engage said set of stationary contacts.
- 50 24. In combination, a selectively operable switching device, an impulse receiving device having a plurality of operating positions, a controlling circuit between said switching device and said receiving device, means operative in response to the operation of said switching device for producing impulses in said controlling circuit, a manually adjustable controller for determining the 55 number of impulses to be sent through said controlling circuit, a registering device for controlling the continuity of said circuit, and switching means for associating said registering device with said controller. 70
25. In a telephone exchange system, a plurality of selectively operable switching devices, a trunk leading to each of said switching devices, a variably operable sender for controlling the setting of any one of said switching devices, a switch associated with said sender and arranged to control its operation, a manually operable controlling device for said switch, an automatic hunting switch having movable and stationary contacts, means for interchangeably associating said movable contacts with said sender and its associated controlling switch, and means including a switch individual to each trunk for associating the stationary contacts of said hunting switch with said controlling device and any one of said trunks. 75
26. In combination, a variably operable sender, controlling means including a plurality of switches for determining its adjustment, means for variably operating said sender in accordance with the adjustment of said controlling means and the operation of said switches, an automatic hunting switch, means for operating the same to associate 80 said controlling means with said sender, and means for successively associating said switches with said sender. 85
27. In combination, a variably operable sender, a controlling circuit therefor, a plurality of variably adjustable controlling switches, means including an automatic hunting switch for extending said controlling circuit towards said switches, means for successively associating the adjusted controlling switches with said extended controlling circuit, and means dependent on the adjustment of said controlling switches for 90 variably operating said sender. 95
28. In combination, a sender, a controlling circuit therefore, means including a plurality of variably adjustable controlling switches for determining the operation of said sender, switching means operative prior to the actuation of said controlling switches for extending said controlling circuit towards said switches, and means for successively associating the actuated controlling switches with 100 said circuit. 105
29. In combination, a plurality of groups of variably adjustable controlling switches, a sender variably operable in accordance with the adjustment of the switches of any one of said groups, a controlling circuit for said sender, means for extending said circuit towards any one of said groups of controlling switches, and a switching means associated with each of said groups for successively associating the actuated controlling 115 switches with said circuit. 120
30. In combination, a plurality of groups of variably adjustable controlling switches, a sender variably operable in accordance with the adjustment of the switches of any one of said groups, a controlling circuit for said sender, means for extending said circuit towards any one of said groups of controlling switches, and a switching means associated with each of said groups for successively associating the actuated controlling 125 switches with said circuit. 130

30. In combination, a plurality of senders, a controlling circuit for each of said senders, a plurality of groups of variably adjustable controlling switches, means for extending any one of said controlling circuits towards any one of said groups of controlling switches, a switching device associated with each of said groups, and means operative upon the actuation of the controlling switches of a group for operating the associated switching device to successively associate the actuated controlling switches with said extended circuit.
31. In combination, a plurality of senders, a controlling circuit for each of said senders, a plurality of groups of variably adjustable controlling switches, each group arranged to control the operation of said sender, means for assigning one of said groups of controlling switches for service, means operative thereupon for extending any one of said controlling circuits towards the assigned group of controlling switches, a switching device for each of said groups of controlling switches, and means operative upon the extension of a circuit towards a group of controlling switches for operating the associated switching device to successively associate the actuated controlling switches with said circuit.
32. In combination, a variably operable sender, a switch, a device operable for controlling the setting of said sender, means responsive to the actuation of said switch for causing said device to operate in part, other means operative in response to the actuation of said switch for causing said device to complete its operation, and means for rendering said two means successively effective.
33. In combination, a variably operable switch, a device having a normal and an actuated position, means operative in response to the actuation of said device for determining the operation of said switch, a controller, means for operating it, means responsive to the operation of said controller for partially actuating said device, means also operative in response to the actuation of said controller for causing the complete actuation of said device, and means for rendering said last two mentioned means successively effective.
34. In combination, a variably operable switch having a plurality of operating positions, electromagnetic controlling means for said switch, means responsive to the energization of said controlling means for causing said switch to move into a certain one of said operating positions, two circuits for said electromagnetic controlling means, simultaneously operating means for preparing the closure of said circuits, and means for successively closing said circuits.
35. In combination, a keyboard, means responsive to the actuation of a key of said

board for producing two sets of impulses of a certain character, a device for registering said two sets of impulses, and means for sending in succession said sets of impulses to said device.

36. In combination, a keyboard, means responsive to the actuation of a key of said board for producing two sets of impulses of a certain character, a sender having a plurality of operating positions, means controllable by said two sets of impulses for moving said sender into a certain position, and means for rendering said sets of impulses successively effective.

37. In combination, a plurality of switches, means responsive to the actuation of each switch for producing two sets of impulses of a definite character, a plurality of devices each arranged to register the sets of impulses produced in response to the actuation of a certain switch, means for rendering the actuation of said switches successively effective, and means for controlling the successive sending of the sets of impulses produced in response to the actuation of a switch.

38. In combination, a plurality of switches, means responsive to the actuation of each of said switches for producing two sets of impulses of a definite character, a plurality of devices, each arranged to register the sets of impulses produced by a certain switch, a controlling switch having a plurality of operating positions, means for moving said controlling switch from position to position, means actuated in operating positions of said controlling switch for sending one of the sets of impulses produced by certain switches, and means operative while said controlling switch is moving from position to position for sending the other sets of impulses produced by said certain switches.

39. In combination, a plurality of switches, means responsive to the actuation of each switch for producing two sets of impulses, a plurality of impulse registering devices, one for registering the sets of impulses produced by each of said switches, a controlling switch having a plurality of operating positions, means for moving said controlling switch from position to position, means operative during the movement of said switch from an operating position into the next operating position for successively associating said switches with their respective registering devices, means operative while said controlling switch is moving between two operating positions for sending one of the sets of impulses produced by a switch, and means operative when said controlling switch is in an operating position for sending the other set of impulses produced by a switch.

40. In combination, a variably operable sender, a plurality of variably adjustable

- devices, means for operating said sender in accordance with the adjustment of said devices, a controller, an automatic hunting switch, a circuit established between said controller and said devices through said automatic hunting switch, and means associated with said devices for successively shifting said circuit from one device to another.
41. In combination, a variably operable sender, a plurality of variably adjustable registering devices, means operable in accordance with the setting of said devices for determining the operation of said sender, a group of switches, means dependent upon the actuation of a certain combination of said switches for operating said registering devices, an automatic switching device, a controlling circuit established between said registering devices and said group of switches through said switching device, means associated with said groups of switches for successively connecting said switches to said controlling circuit, and means associated with said registering devices for successively connecting said registering devices to said controlling circuit.
42. In combination, a plurality of switches, means responsive to the actuation of each switch for producing two sets of impulses of various character, a plurality of devices, one for registering the sets of impulses produced by each of said switches, means for successively associating said devices with the respective switches, and a common means for said devices for adjusting each device to successively receive and register the two sets of impulses.
43. In combination, a keyboard, a group of variably operable electromagnetic devices, means operable in response to the actuation of a certain key of said board for actuating a certain one of said devices, a controlling circuit between said keyboard and group of devices, means associated with said keyboard for successively associating the actuated keys with said circuit, and means associated with said group of devices for successively associating said devices with said circuit.
44. In combination, a keyboard, a group of variably operable electromagnetic devices, means operable in response to the actuation of a certain key of said board for actuating a certain one of said devices, a sender operable in accordance with the actuation of said devices, a controlling circuit between said keyboard and group of devices, a switch for said keyboard for successively associating the actuated keys with said circuit, another switch common to said group of devices, means for actuating said other switch to successively associate said devices with said sender.
45. In combination, a plurality of switches, a plurality of electromagnets, a controlling circuit, a switching device for successively associating said switches with one end of said circuit, other switching devices for successively associating said magnets with the other end of said circuit, and means controlled by one of said switching devices for operating the other switching device.
46. In combination, a plurality of variably operable registering devices, a plurality of switches, a controlling circuit, a switching device for successively connecting the operated switches to one end of said controlling circuit, another switching device for successively connecting the registering devices to the other end of said circuit, and means controlled by one of said switching devices for controlling the operation of the other switching device.
47. In combination, a plurality of switches, each representing a certain value, a plurality of registering devices, each representing a certain value, a controlling circuit between said switches and devices, switching means for successively associating said switches with said circuit, another switching means for successively associating said devices with said circuit, and means under the joint control of said two switching means for rendering simultaneous the said association of a switch and a device of the same value with said circuit.
48. In combination, a plurality of variably operable registering devices, a plurality of switches, means for operating said registering devices in accordance with the actuation of said switches, a controlling circuit, a switching device for successively associating said switches with one end of said controlling circuit, another switching device for successively associating said registering devices with the other end of said circuit, and an operating circuit for said switching devices controllable by both of said switching devices.
49. In combination, a plurality of switches, means responsive to the actuation of each of said switches for producing two sets of impulses of a definite character, a plurality of devices, one for registering the sets of impulses produced by each switch, a controlling circuit between said switches and devices, a switching means for successively associating said switches with said controlling circuit, another switching means for successively associating said devices with said controlling circuit, means including said first mentioned switching means for successively sending the sets of impulses produced by a switch, means associated with the other switching means for causing each of said devices to successively register the sets of impulses produced by a switch, and means con-

trolled by one of said switching devices for controlling the operation of the other switching device.

50. In combination, a plurality of switches, means responsive to the actuation of each switch for producing two sets of impulses of a different character, a plurality of devices, one for registering the sets of impulses produced by each switch, a controlling circuit extending between said switches and devices, two switching devices having a plurality of positions, means under the joint control of said switching devices for causing their movement from position to position, 10 means operative while the said switching devices are moving from one position into the next for associating a certain switch and its corresponding register with the controlling circuit, means operative while said 15 switching devices are moving between two operating positions for effecting the registration of one set of impulses produced by a switch, means operative while said switching devices are in an operating position for 20 effecting the registration of the other set of impulses produced by a switch, an operating circuit for each switching device, and means controlled by one of said switching devices for operating the circuit of the other switching 25 device.

51. In combination, a plurality of switches, means responsive to the actuation of each switch for producing two sets of impulses of a definite character, a plurality of devices, one for registering the sets of impulses produced by each switch, two switching devices having a plurality of positions, means under the joint control of said switching devices for causing their movement from position to position, means operative while the said switching devices are moving from one position into the next for associating a certain switch and its corresponding register with the controlling 40 circuit, means operative while said switching devices are moving between two operating positions for effecting the registration of one set of impulses produced by a switch, means operative while said switching devices are in an operating position for effecting the registration of the other set of impulses produced by a switch, an operating circuit for each switching device, and means controlled by one of said switching devices for operating the circuit of the other switching 45 device.

52. In combination, a plurality of switches, means responsive to the actuation of a switch for producing electrical current impulses, a plurality of impulse receiving devices, an impulse sending circuit between said switches and devices, an electromagnetic switch for controlling the successive sending of impulses produced in response to the actuation of said switches.

through said circuit, another electromagnetic switch for controlling the successive association of said receiving devices with said circuit, and means operable through said circuit for controlling the operation of one of said electromagnetic switches. 70

53. In combination, a plurality of switches, means responsive to the actuation of a switch for producing electrical current impulses, a plurality of impulse receiving devices, an impulse sending circuit between said switches and devices, an electromagnetic switch for controlling the successive sending of impulses produced in response to the actuation of said switches through said circuit, another electromagnetic switch for controlling the successive association of said receiving devices with said circuit, and means operable through said circuit for controlling the operation of said electromagnetic 80 switches. 85

54. In combination, a plurality of switches, means responsive to the actuation of a switch for producing electrical current impulses, a plurality of impulse receiving devices, an impulse sending circuit between said switches and devices, an electromagnetic switch for controlling the successive sending of impulses produced in response to the actuation of said switches through said circuit, another electromagnetic switch for controlling the successive association of said receiving devices with said circuits, and means controlled by said impulses for operating one of said electromagnetic switches. 90 95

55. In combination, a plurality of switches, means responsive to the actuation of a switch for producing electrical current impulses, a plurality of impulse receiving devices, an impulse sending circuit between said switches and devices, an electromagnetic switch for controlling the successive sending of impulses produced in response to the actuation of said switches through said circuit, another electromagnetic switch for controlling the successive association of said receiving devices with said circuit, and means controlled through said circuit by said impulses for controlling the operation of said electromagnetic switches. 105 110 115

56. In combination, a plurality of switches, means responsive to the actuation of various switches for producing electrical current impulses of various character, a plurality of responsive devices variably operable depending on the character of said impulses, an impulse sending circuit between said switches and devices, an electromagnetic switch for controlling the successive sending of impulses produced by said switches through said circuit, another electromagnetic switch for controlling the successive association of said responsive devices with said circuit, and means operable through said circuit by impulses of any character 120 125 130

- for operating one of said electromagnetic switches.
57. In combination, a plurality of switches, means responsive to the actuation of various switches for producing electrical current impulses of various character, a plurality of responsive devices variably operable depending on the character of said impulses, an impulse sending circuit between said switches and devices, an electromagnetic switch for controlling the successive sending of impulses produced by said switches through said circuit, another electromagnetic switch for controlling the successive association of said responsive devices with said circuit, and means operable through said circuit by impulses of any character for operating said electromagnetic switches.
58. In combination, five switches, a register comprising three relays, means operative in response to the actuation of a switch for energizing all of said relays, means responsive to the actuation of a second switch for energizing the first and second relays, and means for preventing the energization of the third relay, means responsive to the actuation of a third switch for energizing the first and third relays, and means for preventing the energization of the second relay, means responsive to the actuation of a fourth switch for energizing the first relay, and means for preventing the energization of the second and third relays, means responsive to the actuation of a fifth switch for preventing the energization of said three relays, and a self-locking circuit for said relays.
59. In combination, a register comprising a marginal and a sensitive relay, circuits for said relays, switches for controlling said circuits, and means variably operable by said switches for changing the resistance of said circuits.
60. In an impulse registering device, two marginal relays and a sensitive relay, a circuit including one of said marginal and the sensitive relay, another circuit including the other marginal relay, a plurality of switches for variably controlling said circuits, means operable by said switches for adjusting the resistance of said circuits, and a self-locking circuit for said relays.
61. In combination, a registering device comprising two marginal relays and a sensitive relay, a circuit including one of said marginal and the sensitive relay, another circuit including the other marginal relay, a plurality of switches for variably controlling said circuits, means operable by said switches for adjusting the resistance of said circuits, a self-locking circuit for said relays, a variably operable device, an electromagnetic controlling means therefor, and contacts for said relays in circuit with said controlling means.
62. In combination, a registering device comprising two marginal relays and a sensitive relay, a circuit including one of said marginal and the sensitive relay, another circuit including the other marginal relay, a plurality of switches for variably controlling said circuits, means operable by said switches for adjusting the resistance of said circuits, a self-locking circuit for said relays, a variably operable sender, electromagnetic stepping and arresting means therefor, a selectively operable switching device, means for operating said switching device, means responsive to the operation of said switching device for operating said stepping means, a circuit for said arresting means, contacts for said relays arranged to control the circuit of said arresting means, and means responsive to the actuation of said arresting means for rendering the operating means of said selectively operable switching device ineffective.
63. In combination, a registering device comprising three relays, circuits for said relays, a variably adjustable controller for said circuits, a variably operable sender, electromagnetic actuating and arresting means for said sender, a selectively operable switching device, motor means therefor, means operative upon the operation of said controller for actuating said motor means, means operative in response to the operation of said selectively operable switching device for operating said actuating means, a circuit for said arresting means, contacts for said relays in said last mentioned circuit, and means operable in response to the actuating of said arresting means for rendering said motor means ineffective.
64. In combination, a registering device comprising a plurality of relays having variably operable contacts, circuits for said relays, a variably operable controller for said circuits, a sender having electromagnetic actuating and arresting means, a selectively operable switching device, motor means therefor, means operative upon the actuation of said controller for causing the operation of said motor means, means responsive to the operation of said switching devices for operating the actuating means of said sender, a circuit for said arresting means jointly controlled by said relay contacts and said sender, and means operative upon the actuation of said arresting means for rendering the motor means of said switching device ineffective.
65. In combination, a registering device comprising a plurality of relays having contacts, circuits for said relays, a variably operable controller for said circuits, a sender having a plurality of operating positions, electromagnetic actuating and arresting means for said sender, a selectively operable switching device, motor means therefor,

means operative upon the adjustment of said controller for actuating said motor means, means operative during the operation of said selectively operable switching device for operating the actuating means of said sender, a normally open circuit for said arresting means leading through all contacts of said relays, and means controlled by said sender for closing said circuit in any one of its positions.

66. In combination, a register comprising a plurality of relays having variably operable contacts, controlling circuits for said relays, a variably operable controller for said circuits, a sender comprising a movable contact and a series of stationary contacts, electromagnetic actuating and arresting means for said movable contact, a selectively operable switching device, motor means therefor, means for operating said motor means upon the actuation of said controller, means responsive to the operation of said switching device for operating said actuating means, a circuit for said arresting means having a plurality of branches each leading to a stationary contact, means for completing said last mentioned circuit through any one of said branches and said movable contact, contacts of said relays controlling said branches, and means operative upon the actuation of said arresting means for rendering said motor means ineffective.

67. In a switch-controlling device, a movable contact, a plurality of stationary contacts arranged in sections, multiple connections between stationary contacts of two sections, means for operating said movable contact to engage any one of said stationary contacts, and means for arresting said movable contact on any one of said stationary contacts.

68. In a switch-controlling device, a series of stationary contacts arranged in sections, a movable contact arranged to wipe over said stationary contacts, an actuating magnet for said movable contact, a relay permanently connected to one pole of a battery for controlling said actuating magnet, means for connecting said relay to any one of said stationary contacts, multiple connections between stationary contacts of two sections, and means for connecting said movable contact to the other pole of the battery only when engaging stationary contacts of a predetermined section.

69. In combination, a selectively operable switching device having a plurality of operating positions, motor means therefor, a variably operable controlling apparatus comprising switches representing various positions of said switching device, means responsive to the actuation of said switches for producing electrical current impulses, a plurality of devices each arranged to register the impulses produced by a certain

switch, three electrical conductors, means for extending said electrical conductors between said controlling apparatus and said devices, means for extending the first one of said conductors to said switching device, means for sending said impulses through the first and second of said conductors for causing the actuation of one of said devices, means for sending the impulses produced by the other switches through the second and third of said conductors for actuating the other devices, and means operable through the first one of said conductors for controlling the operation of said switching device in accordance with the setting of a registering device.

70. In combination, a variably operable switching device, electromagnetic controlling means therefor, a circuit for said controlling means having a plurality of branches, a switch in each of said branches and in the common portion of said circuit, means responsive to the actuation of the switch in the common portion of the circuit for moving said device into either of two operating positions, means responsive to the actuation of the contact in one of said branches for arresting said device in one of said two operating positions, and means responsive to the actuation of the contact in the other branch for arresting said switch in the other one of said two operating positions.

71. In a telephone exchange system, a selector switch, a sender having a plurality of operating positions, means for variably operating said selector switch in accordance with the operating position occupied by said sender, controlling means for said sender, means responsive to the actuation of said controlling means for causing said sender to move toward a certain operating position, and means also responsive to the actuation of said controlling device for arresting said sender before it reaches said operating position.

72. In combination, a sender having a movable and a plurality of stationary contacts, a selectively operable switching device, a relay for controlling the same, a relay for causing the advance of said movable contact from one stationary contact to the other, means for establishing a circuit including said relays, a third relay arranged to operate to open said circuit upon energization, a plurality of controlling switches less in number than said stationary contacts, a circuit having two branches, means controlled by said movable contact when engaging certain stationary contacts for closing one of said branches, separate means controllable at will for closing the other one of said branches, and a common portion for said circuit including said second relay and the actuated controlling device.

73. In combination, a selector switch comprising a set of movable contacts and ten sets of stationary contacts, a series of ten switches each representing a certain one of 5 said sets of stationary contacts, means responsive to the actuation of each of five of said switches for producing impulses of various character, means for producing said impulses of various character in response 10 to the actuation of the other five switches, a device for registering the impulses produced by said switches, a sender, means for operating said sender in accordance with the setting of said registering device, means for 15 operating said movable contacts in accordance with the operation of said sender, means depending on the setting of said registering device for causing the sender to take one to five steps, and other means operable in response to the actuation of the other 20 five switches for causing said sender to take one to five additional steps.
74. In combination, operators' positions, a variably operable register sender, a plurality of sender controlling devices at said operators' positions, normally disassociated from said sender and located at various 25 distant points with regard to the sender and to each other, and means for associating any 30 one of said sender controlling devices with said sender.
75. In combination, an operator's position, a plurality of variably operable senders, a plurality of keys at the operator's position 35 for determining the operation of said senders, said keys being normally disassociated from said senders, and automatic means for associating said keys with any one of said senders, and means for rendering said keys 40 effective in succession to determine the operation of the associated sender.
76. In combination, an operator's position, a plurality of variably operable senders, a controlling device at the operator's 45 position for determining the operation of said senders, said device being normally disassociated from said senders, a plurality of automatically operable hunting switches, means for operating said switches simultaneously to associate said controlling device 50 with any one of said senders.
77. In combination, an operator's position, a plurality of variably operable senders, a controlling device at the operator's 55 position for determining the operation of said senders, said device being normally disassociated from said senders, a plurality of automatic hunting switches, means for allotting said switches for use, 60 and means for operating the allotted switches to associate said controlling device with any one of said senders.
78. In combination, an operator's position, a plurality of variably operable 65 senders, a keyboard at the operator's posi-
- tion for determining the operation of said senders, said keyboard being normally disassociated from said senders, and a plurality of automatic hunting switches cooperating with each other for associating said keyboard with any one of said senders. 70
79. In combination, an operator's position, a plurality of variably operable senders, a controlling device at the operator's position for determining the operation 75 of said senders, said controlling device being normally disassociated from said senders, a group of trunks at said position, and a plurality of automatic hunting switches simultaneously operable for associating said 80 controlling device and one of said trunks with any one of said senders.
80. In combination, an operator's position, a plurality of switch controlling mechanisms each including a plurality of registers, a controlling device at the operator's position for determining the setting of said registers, said device being normally disassociated from said mechanisms, and automatic selectively operable switching means 85 for associating said device with any one of said mechanisms. 90
81. In combination, an operator's position, a plurality of switch controlling mechanisms each including a plurality of registers, a controlling device at the operator's position normally disassociated from said mechanisms, selectively operable switching 95 means for associating said controlling device with any one of said mechanisms, and means responsive to the operation of said controlling device for variably setting in succession the registers of the associated mechanism. 100
82. In combination, an operator's position, a plurality of switch controlling mechanisms each including a plurality of registers, a plurality of keys at the operator's position for variably setting said registers, said keys being normally disassociated from 105 said mechanisms, selectively operable switching means for associating said keys with any one of said mechanisms, and means for rendering said keys effective to set in succession the registers of the associated mechanism. 110
83. In combination, an operator's position, a plurality of switch controlling mechanisms each including a plurality of relay registers, a keyboard at the operator's position for variably operating the registers of 120 said mechanisms, said keyboard being normally disassociated from said mechanisms, and selectively operable switching means for associating said keyboard with any one of said mechanisms. 125
84. In combination, a plurality of operators' positions, a plurality of variably operable senders, controlling devices at each of said positions for determining the operation of said senders, said devices being normally 130

disassociated from said senders, a plurality of automatic hunting switches, and means for operating said switches simultaneously to associate any one of said controlling devices with any one of said senders.

85. In combination, a plurality of operators' positions, a plurality of variably operable senders, controlling devices at each of said positions for determining the operation 10 of said senders, said controlling devices being normally disassociated from said senders, a plurality of automatic hunting switches, means for allotting said switches for use, and means for operating the allotted 15 switches for associating any one of said controlling devices with any one of said senders.

86. In combination, a plurality of operators' positions, a plurality of variably operable senders, controlling devices at each of 20 said positions for determining the operation of said senders, said controlling devices being normally disassociated from said senders, switching means for each of said operators' positions, means for allotting for use 25 the switching means individual to any particular one of said positions, and means for operating said switching means to associate the controlling device at said particular position with any one of said senders.

87. In combination, a plurality of operators' positions, a plurality of switch controlling mechanisms each including a plurality of variably adjustable registers, a controlling device at each of said positions for 30 adjusting the registers of said mechanisms in accordance with desired designations, said controlling devices being normally disassociated from said mechanisms, and selectively operable switching means for associating 35 any of said controlling devices with any one of 40 said mechanisms.

88. In combination, a plurality of selective switches for establishing telephone connections, a plurality of operators' positions, a plurality of switch controlling mechanisms 45 each including a plurality of variably adjustable registers, a keyboard at each operator's position for adjusting the registers of said mechanisms in accordance with desired 50 designations, said keyboards being normally disassociated from said mechanisms, an automatic switching means for associating any one of said keyboards with any one of said mechanisms, and means controlled in accordance 55 with the adjustment of the registers of the associated mechanism for operating said selective switches.

89. In a telephone exchange system, the combination with a plurality of groups of 60 connecting circuits, automatic switching apparatus for extending said connecting circuits, a plurality of primary controlling devices individually associated respectively with the several groups of connecting cir-

cuits, a common group of secondary controlling devices, and automatic switching means operable when a call is extended to a connecting circuit in any group for associating the primary controlling device of that group and any one of said secondary controlling 70 devices with said connecting circuit.

90. In a telephone exchange system, the combination of a plurality of connecting circuits, automatic switching means for extending said connecting circuits, a plurality 75 of primary and a plurality of secondary switch controlling devices, and automatic means operable when a call is extended to a connecting circuit for associating therewith a primary and any one of said secondary 80 switch controlling devices.

91. In a telephone exchange system, the combination with a plurality of groups of connecting circuits, automatic switching apparatus for extending said connecting circuits, a plurality of primary controlling devices individually associated respectively with the several groups of connecting circuits, a common group of secondary controlling devices including a plurality of 90 registers arranged to be operated by said primary devices, and automatic switching means operable when a call is extended to a connecting circuit in any group for associating the primary controlling device of 95 that group and any one of said secondary controlling devices with said connecting circuit.

92. In a telephone exchange system, the combination with a plurality of groups of 100 connecting circuits, automatic switching apparatus for extending said connecting circuits, a plurality of primary controlling devices individually associated respectively with the several groups of connecting circuits, a common group of secondary controlling devices, and a plurality of simultaneously operable switches actuated when a call is extended to a connecting circuit in any group for associating the primary controlling device of that group and any one of 110 said secondary controlling devices with said connecting circuit.

93. In a telephone exchange system, the combination of a plurality of connecting circuits, automatic switching means for extending said connecting circuits, a plurality of controlling devices, a plurality of switch controlling register senders, and automatic beans operable when a call is extended to a 115 connecting circuit for associating therewith a controlling device and any one of said switch controlling register senders.

In witness whereof I hereunto subscribe my name this 28th day of December A. D. 125 1916.

ALBEN E. LUNDELL.
